Application September 23, 1921, Serial No. 502,626
Renewed April 9, 1926

127 Claims. (Cl. 179—27)

The present invention has for its broad objects the improvement of telephone systems in general, and more particularly automatic and semi-automatic telephone systems, looking toward the 5 affording of operative conveniences to users and benefits to the operating concern which have been heretofore unknown.

The invention in its specific form chosen for the illustration herein, contemplates a so-called 10 two-wire common battery automatic telephone system as has been widely used, the present invention necessitating novel departures from equipments heretofore known so far as I am aware, in attaining the new objects, while retaining 15 certain operative functions which are known.

The exemplified form of the present invention chosen to illustrate it contemplates its adaptation to a comprehensive four-digit automatic telephone exchange system. However, the present 20 invention is more particularly directed to that part of a comprehensive automatic telephone exchange system as relates to groups of subscriber's lines and to toll and special service.

In comprehensive automatic exchange systems 25 there are various classes of subscribers, each demanding more or less special service and presenting varied operating conditions. For example, certain subscribers generally termed individual subscribers, have a single or isolated local line 30 used for in-going and out-going traffic between the subscriber's premises and the main exchange. Other subscribers have a plurality of such lines, known as a group. Where a group of lines serves a subscriber it has been a practice heretofore 35 to list one telephone number so that if this number is called the group of lines will be reached and a first idle one thereof seized and rung upon, so that the operation so far as the calling subscriber is concerned is the same when calling a 40 subscriber having an individual line, or a group of lines serving his traffic.

Where a group of lines extend to the premises of a subscriber they usually terminate in a private branch exchange switchboard, the calls being 45 answered by an attendant or operator, and then extended to any desired local telephone terminating in the private branch-exchange switchboard. Under this plan of operation, when the operator is absent, at night or on holidays, for 50 example, it has been a practice to connect certain ones of the lines of the group to certain local telephones so that a call coming in over one of the thus connected lines of the group will signal the connected telephone directly, and may be answered by anyone near the concerned local tele-

phone. Going further, it has been a practice to specially list certain telephone numbers which are comprised in the group, or which may not be comprised in the group but are in common relation therewith in the main office by reason 60 of the bank contacts corresponding to special non-group-selecting connector bank numbers listed being in multiple relation with the corresponding connector bank contacts leading to the concerned line (or lines) of the group, so that as 65 a matter of fact, the concerned line is reachable by calling the regular listed telephone number accessible to a group-selecting connector, or by calling a specially listed telephone number accessible to a non-group-selecting connector. The 70 above practice refers more particularly to private branch exchange subscribers having one or more employes available at one or more specific telephones in the private branch exchange at nights and on holidays, for example and, therefore, affords a means of directing a call at these times to 75 the special telephone.

Due to the inherent characteristics of the connectors heretofore known so far as I am aware (such as connector C in Fig. 4 of my Patent No. 80 1,506,054, granted Aug. 26, 1924) which automatically select a non-busy line of a group when the telephone number indicative of the entire group is called, confusion is often entailed. For example, if the local telephone connected to corresponding with the specially listed telephone number comprised in the group is busy, and therefore, the line of the group corresponding 85 with the specially listed telephone number is guarded against intrusion, the group selecting 90 connector concerned in a call transpiring will automatically select the first non-busy line of the group following. This will either signal a telephone not wanted on the premises of the subscriber or it will seize a trunk line that has no 95 connected extension from the private branch exchange switchboard and, therefore, will not be answered. Of course, where auxiliary or special numbers are assigned in non-group selecting connectors corresponding to specific lines 100 comprised in the groups as has been referred to, this will not occur, because if the line called is busy the connection cannot be completed to an alternative line. However, such a method as the latter comprehends the use of additional equipment involved in the special numbers accessible to the non-group-selecting connectors, whereas each line of a group otherwise has a specific 105 telephone bank number, accessible to a group-selecting connector, but as referred to, if the 110

specific line of the group is busy an alternative line of the group will be selected unless, of course, the line is the last line of the group. The latter would only be possible where a single special number is connected for night and holiday use.

a. The present invention contemplates, among other novel functions, and the equipments for effecting them, a group-selecting connector which is normally a non-group-selecting connector, but which is transformed into a group-selecting connector, consequent to the first bank position of a subscriber's group being encountered in a call from a subscriber's station, regardless of whether the line leading therefrom tests busy or not. From this it will appear that the connector of the present invention referred to will not rotate as a group-selecting connector if a telephone number specific to a line of the group other than the line occupying the first bank position of the group is called. The present invention then, permits of any of the lines occupying bank positions in a group other than the first bank position thereof being connected to a local telephone in a private branch exchange and insures that a call directed to the listed telephone number corresponding to the specific line of the group will attain connection to the desired local telephone or will give a busy signal to the calling party.

Auxiliary to inter-subscriber switching, comprehensive exchange systems in nearly all cases contemplate the switching of toll lines to the local lines leading to the premises of subscribers. This switching is, in nearly all cases, controlled or effected by an operator located at a toll switchboard situated within the confines of the exchange district, which shall be termed "the exchange toll operator" and "the exchange toll switchboard", respectively, or at some remote point wherein the switching connection is established by controlling automatic switching equipments over the toll line from which the connection to the subscriber is desired.

b. Depending upon the traffic, various means for rendering this service to the subscribers have been employed. Where the traffic of a toll nature is very light and the local traffic is also light and not apt to interfere seriously with the toll traffic, toll calls are routed over the same lines from the main exchange to the premises of the subscriber as are used for local traffic, though it has been a practice to provide specific switching apparatus in the main exchange for attaining connection to the local lines through convertible connectors in common with the local apparatus directed by subscribers.

c. Another method which has been employed is that of providing an independent line between a spring-jack on the exchange toll switchboard and the subscriber's premises reserved exclusively for toll service to the subscriber and for the use of the subscriber in calling the exchange toll operator. These shall be termed "manual toll loops". The exchange toll operator, under this method of operation, extends the call by means of a switching cord-pair.

d. Another method which has been employed is that of providing an independent line from a subscriber's premises to a toll automatic switching system, independent of the local automatic switching system, whereby the exchange toll operator can call over the independent line to the subscriber automatically through a cord-pair, through the agency of a dial or other

equivalent calling device. These shall be termed "automatic toll loops". Systems of this kind have, in cases, been accessible not only from the exchange toll switchboard located within the confines of the exchange district, but also accessible to toll operators at toll switchboards located remotely, wherein the establishment of the connection is controlled over the toll line from which the connection to the subscriber is desired. The latter shall be termed "the remote toll operator" and "the remote toll switchboard", respectively.

An undesirable feature involved in the methods set forth under paragraph "c" is that the exchange toll operator upon receiving the call for the subscriber from a distant point must know off-hand that the called subscriber has a special toll loop, so the call can be completed through a switching cord-pair. In view of the fact that in many cases calls are given by calling parties by number, and that it is quite impossible to mentally retain the information relating to all subscribers in large systems and that it is not always convenient to consult an authentic special directory, the calls are very often routed over the regular exchange local lines to the subscribers, causing annoyance. Again, these manual toll loops not being accessible to operators located remotely, will mean that all remotely completed calls to a called subscriber over the toll lines will reach the subscribers' premises over the regular exchange local line and, as before stated, cause annoyance.

An undesirable feature involved in the method set forth under paragraph "d" is that the exchange toll operator on receiving a call from a distant toll station for a local subscriber must know that the called subscriber has a special automatic toll loop. Also, the remote toll operator calling for the subscriber automatically must know off-hand that the called subscriber has a special automatic toll loop, the same as where the toll loop terminates on a springjack on the exchange toll switchboard reachable from the calling toll line through a switching cord-pair. So it is necessary for the remote toll operator who may be calling over a toll line automatically, to have this information or it will be completed under control of the remote toll operator over the regular exchange local line (or one of the exchange local lines) of the subscriber, causing annoyance.

e. The present invention, wherein it relates to independent toll loops (manual and automatic) to the premises of local subscribers comprehends means for automatically apprising the calling toll operator (located in the main exchange district or at a remote point connected over a toll line), that the subscriber whose listed local number has been called, has an independent toll loop as has been referred to in paragraphs "c" and "d". Depending upon the tone received, it may mean that the subscriber has an independent toll loop occupying the first bank position of the group accessible to the group-selecting connector used by the local subscribers in calling and also by the toll operators, which shall be termed "the exchange toll loop", but that this exchange toll loop is only accessible to a toll operator calling through the special toll selectors, and is not accessible to a local subscriber calling through the local selectors.

f. A further function of the group-selecting connector referred to in paragraph "e" is that if the toll operator receives the tone indexing that

the called subscriber has an exchange toll loop accessible through the group-selector connector then functioning, and also receives a tone auxiliary thereto indicative that the exchange toll loop is busy, the toll operator can, by sending digit "1", cause the group-selecting connector to forthwith start functioning as a group-selecting connector and seize the first disengaged local exchange line. If the exchange toll loop is not busy the connection can be completed normally, but the connector will not function as a group-selecting connector, when reached from a toll selector, unless the digit "1" is sent to initiate its functioning as a group-selecting connector regardless of the busy or idle state of the exchange toll loop primarily called.

g. A further function of the group-selecting connector referred to in paragraph "f" is that should the toll operator call an intermediate line of a group it will not function as a group-selecting connector unless digit "1" is sent to initiate such functioning, regardless of whether the intermediate line called is idle or busy.

h. A further function of the group-selecting connector referred to in paragraph "g", is that if the toll operator, upon calling an intermediate line of a group, receives a busy tone and the operator then sends the digit "1", causing the connector to function as a group-selecting connector, whereupon it seeks an idle line of the group of local lines, but fails to find a disengaged one, upon engaging the last tank position of the group applies the customary busy-tone indicative that there are no idle lines in the group. The operator can, by sending an additional digit "1", cause the connector to be released to normal position. The selector co-operating with the connector still maintains its seizure and thus enables a call to be completed through the connector to a line of the group last concerned, or to any other line accessible to the connector, by calling two digits, whereupon the connector will function as if it has primarily reached the last line called, and had not been released. A further function of the group-selecting connector, effective when it is co-operated with a toll selector, is that when it is seized by the cooperating toll selector, it applies a specific tone audible to the calling toll operator indicative that the connector is seized, and moreover, that it is at normal position, since the said tone is disassociated consequent upon the first off-normal movement of the shaft.

i. In view of paragraphs "e" and "f" it will appear that, if through inadvertence, the toll operator ignores the fact that the called subscriber has a manual toll loop terminating in a springjack on the exchange toll switchboard, a specific tone will be applied audible to the calling operator upon the connector attaining the called bank position corresponding to the called line, regardless of its busy or idle state, prompting the fact there is such a toll loop, so the connection can be taken down and properly routed.

j. It will appear that the present invention enables the toll operator, wherever located, to reach the called subscriber over his telephone number listed in the general subscribers' directory and it will also appear that this exchange toll loop is barred against seizure by a local subscriber calling the subscriber having the exchange toll loop, through local selectors; such calls being directed to a local line of the group.

k. Another connector contemplated under the present invention is a non-group-selecting connector used for completing a connection to a

subscriber's local line, that will function to project a specific tone audible to a calling toll operator indicative that the subscriber called has a manual toll loop terminating in a springjack on the exchange toll switchboard, or has an automatic toll loop, perhaps, which can be reached through an auxiliary automatic toll exchange. The tone function referred to is dependent in a measure upon functions of the toll selector co-operating with the connector and, therefore, the said tone will not be operative to local subscribers calling through local selectors to the connector.

l. The shaft of the connector referred to in the last foregoing paragraph can be released to normal position under control of the toll operator if the line selected, called through a toll selector, tests busy or the connector seizes. This releasing cannot be effected by a local subscriber calling through a local selector. Of course, the tone thus applied may index any other condition relating to the called subscriber, such as to prompt the calling operator to refer to the credit record, etc. In fact it is contemplated, as will appear, to have a plurality of tone sources interchangeably connected in relation to the subscriber's equipment so that various tones will be connectible to prompt any single one or a plurality of specific facts concerning the called subscriber, and other callable subscribers.

m. A function of the present invention relates to the toll loops referred to in paragraphs "e" and "f", wherein if the telephone terminating the exchange or automatic toll loop is removed from the switchhook when the line is normal in order to initiate a call to the toll switchboard, an outgoing call, for example, it will cause a local inter-office general traffic trunk to be seized and the call automatically directed and completed to the recording position of the exchange toll switchboard, without special operation on the part of the calling subscriber. It will thus appear that where an exchange is made up of a plurality of main-branch offices the independent exchange and automatic toll loops of subscribers will be connected into the same main-branch offices as the local lines of the concerned subscribers.

Other novel functions and features, as well as the invention itself, will appear.

In the accompanying drawings:—

Fig. 1 shows an automatic telephone L leading into a lineswitch LS, and the latter in common with other lineswitches (not shown) have access to a first selector FS. The first selector FS in common with other first selectors (not shown) have access to second selector SS. The second selector SS, in common with other second selectors (not shown) have access to connectors A and F.

Fig. 2 shows a group-selecting connector A which has access to cooperating bank contacts.

Fig. 3 shows two local automatic subscribers' lines and an exchange toll loop accessible to connector A.

Fig. 4 shows a toll selector B which has access through cooperating bank contacts with connectors A and F.

Fig. 5 shows an operator's switching cord-pair C adapted to cooperate with springjack D leading to toll first selector E. Selector E in common with other first selectors similar to it (not shown) have access to second selector B.

Fig. 6 shows a non-group selecting connector F which has access through cooperating bank contacts to two subscribers' local lines.

Fig. 7 shows a normal-level selector I terminating an inter-office trunk. Through its normal

level it has access to equipments H located on a recording position of the exchange toll switchboard. Through its first level, and other levels not shown, calls can be forwarded in the direction of called local subscribers' lines.

Fig. 7A shows a novel mechanical detail of two companion relays in Fig. 7 wherein one of the relays is shown operated, restraining the other.

Fig. 8 shows a schematic arrangement of two banks of contacts, such as are shown cooperating with connector A of Fig. 2, but in more detail. The bank contacts designated J correspond to the bank contacts shown cooperating with the said connector A, while the banks designated K represent one of a plurality of banks which cooperate with connectors similar to said A of the connector group. It will thus be clear that the bank contacts shown in the bank cooperating with said A are in multiple relation respectively with the contacts of banks cooperating with a plurality of respective connectors similar to said A of the group. The conductors leading from the respective multiplied contacts located in corresponding relation to the respective connectors of the group lead to terminals from which the connections contemplated under the present invention can be made and altered from time to time without consideration of each bank individually.

Fig. 9 shows a toll line leading from a spring-jack L on the exchange toll switchboard to a remote toll station telephone T9.

Fig. 10 shows a manual toll loop leading from a springjack M on the exchange toll switchboard to a subscriber's toll telephone T10.

Fig. 11 shows the arrangement of the figures concerned in a call from the exchange toll switchboard to toll loop telephone T23 or to local telephones L12 and L24.

Fig. 12 shows the arrangement of the figures concerned in a call from local telephone L to local telephones L12 or L24.

Fig. 13 shows the arrangement of figures concerned in a call from local telephone L to local telephones L6 or L6'.

Fig. 14 shows the arrangement of the figures concerned in a call from toll loop telephone T23 to the exchange toll switchboard.

Fig. 15 shows the arrangement of the figures concerned in a call from the toll switchboard to local telephones L6 or L6'.

Fig. 16 shows the relative location of the sets of bank contacts in the bank cooperative with connector A with respect to the bank positions thereof.

Referring to certain of the various figures:—

In Fig. 1, L is a usual series type of automatic telephone having a calling device 102 of the general class as shown in British patent to Dicker No. 29,654 of 1910. The lineswitch LS is of the general class as shown in U. S. patent to Lamb, No. 1,193,160, granted August 1, 1916. The first selector FS is of the general class as shown in U. S. patent to Keith and Erickson, No. 815,321, granted March 13, 1906, of course, modified in mechanical and circuit details to operate on the well known so-called two-wire principle and in accordance with the present invention. The second selector SS is similar in detail to first selector FS. In this connection it may be stated that telephone L, lineswitch LS, first selector FS and second selector SS, may for the purposes of elucidating the present invention, be considered as telephone A, lineswitch C, first selector E and second selector F shown in the patent reissued to

Frank Newforth, April 13, 1915, numbered 13,901.

In Fig. 2 the novel group-selecting combination local and toll connector A is of the general class as shown in U. S. patent to Keith and Erickson, No. 815,176, granted March 13, 1906, of course, modified in mechanical and circuit details to operate on the well known so-called two-wire principle and in accordance with the present invention.

In Fig. 3 telephones L12, L24, T23 and E3 may be considered similar in detail to telephone L. Lineswitch LS3' may be considered generally similar to LS. Relays 301 and 302 may be considered as representing lineswitches similar to LS. Lineswitch LS3 may be considered similar in detail to lineswitch LS. First selector FS3 may be considered similar in detail to selector SS. Repeater R3 is a novel device for localizing the battery supply to a calling telephone and for repeating impulses to switches interlinked in the direction of the called line.

In Fig. 4 the novel toll selector B, adapted for cooperating with combination local and toll connectors A and F, belongs to the general class to which selector FS belongs.

In Fig. 5 the toll first selector E belongs to the general class to which selector FS belongs, and is well known in the art.

In Fig. 6 the novel non-group selecting combination local and toll connector F belongs to the general class to which connector A belongs. Telephones L6 and L6' may be assumed similar in detail to telephone L.

In Fig. 7 the novel normal-level selector I belongs to the general class to which selector FS belongs. Connector CS7 may be assumed similar in detail to connector F. Telephone L7 may be assumed similar in detail to telephone L. Relay 700 may be assumed to represent a lineswitch similar in detail to LS.

In Fig. 9 telephone T9 is a well known type of bridging local battery telephone.

In Fig. 10 telephone T10 is a well known type of non-automatic local battery telephone.

To simplify the drawings and descriptions, battery and ground are shown as independent sources throughout, wherever applied, but it is to be understood that the system is of the common battery type. In the descriptions, when a circuit is traced to a winding, the opposite terminal of which is shown applied to grounded battery or to ground, the described circuit is to be considered as traced to ground through the winding to battery, or direct to ground as indicated.

The performance of the equipments will be detailed under different assumed operative conditions, having in mind that the equipment elements may be, and in fact, ordinarily would be variously organized in the assembly of a system.

Referring to the accompanying drawings:—

With reference to Fig. 13, it will be assumed that a call from telephone L is to be extended to called telephone L6, the telephone number of which is "1212". Upon the calling subscriber removing the receiver from the switch-hook of telephone L, lineswitch LS will automatically seize a trunk to a disengaged first selector FS. Upon sending the first digit "1" by manipulating the calling device 102 in accordance therewith, selector FS will step its wipers into alignment with the first level of its bank contacts and automatically rotate-in and seize a trunk leading to an idle second selector SS. Upon sending the second digit "2" selector SS will step its wipers into alignment with the second level of its bank

- contacts and automatically rotate-in and seize a trunk leading to an idle connector F.
- A circuit can now be traced from the upper winding of relay 601, make-before-break spring 602, conductor 603, wiper 101, conductor 102, wiper 103, conductor 104, wiper 105, conductor 106, through receiver of telephone L, conductor 107, wiper 108, conductor 109, wiper 110, conductor 111, wiper 112, conductor 113, make-before-break spring 604 to the lower winding of relay 601, relay 601 actuating. A circuit can now be traced from the winding of slow-releasing relay 606 to grounded armature 607, relay 606 actuating. Grounded armature 608 applies its ground to conductor 609, wiper 114, conductor 115, wiper 116, conductor 117, wiper 118 to the winding of cut-off relay 119 of lineswitch LS, maintaining the said lineswitch in the well known manner.
- Upon the calling subscriber sending the third digit "1", relay 601 will de-actuate and re-actuate one time. Ground from armature 607 will be applied to armature 612, armature 613, series winding of slow-releasing relay 614, winding of vertical magnet V6, sideswitch wiper 615 to grounded battery, causing relay 614 to actuate, and to operate the vertical magnet one time to step the shaft carrying wipers 616 to 619 (inclusive) into alignment with its first bank level. Incidental to the operation of relay 614, grounded armature 620 engages make-before-break spring 621 and applies ground to the winding of private magnet P6, energizing it preparatory to permitting the sideswitch wipers 615 and 622 to advance into their second position. Upon relay 614 de-actuating its period after the opening of the energizing circuit including the winding of vertical magnet V6, the sideswitch wipers 615 and 622 will advance into their second position.
- Upon the calling subscriber sending the fourth digit "2", relay 601 will deactuate and re-actuate two times. Armature 607 will apply its ground two times over a circuit including armature 612, armature 613, winding of relay 614, armature 624, winding of rotary magnet R6, sideswitch wiper 615 to grounded battery, causing relay 614 to actuate and operate the rotary magnet two times to step the wipers 616 to 619 into engagement with bank contacts 625 to 628 respectively. Upon relay 614 de-actuating its period after the opening of the energizing circuit including the winding of rotary magnet R6, the sideswitch wipers 615 and 622 will advance into their third position. A circuit can now be traced from ground, sideswitch wiper 622, winding of relay 629, sideswitch wiper 615 to grounded battery, relay 629 actuating. A circuit can also be traced from ground sideswitch wiper 622, wiper 617, bank contact 626 to the winding of cut-off relay 630 of the lineswitch similar to LS associated with the line leading to L6, disassociating it from the telephonic conductors of the said line in the well known manner.
- A circuit can now be traced from grounded interrupted ringing current source G6, armature 631, armature 632, armature 633, armature 634, wiper 619, bank contact 628, signal bell at telephone L6, bank contact 627, wiper 618, armature 635, armature 636, armature 637, armature 638, inner winding of relay 640 to grounded battery. The signal bell 641 of telephone L6 which includes condenser 642 will be operated, but the characteristic of relay 640 is such that it will not be operatively energized by the said ringing current. However, upon the response of the called party,
- wherein the receiver at telephone L6 is removed from the switchhook, a conductive circuit can be traced from grounded ringing current source G6 over the traced path, now including the receiver of telephone L6. Relay 640 will operate. A locking circuit for relay 640 can now be traced from its outer winding, armature 643, conductor 644 to grounded off-normal spring 645. Off-normal spring set ON6 is adjusted to close its contacts upon the first off-normal movement of the shaft carrying wipers 616 to 619.
- A circuit can now be traced from upper winding of relay 646, conductor 647, armature 636, over the traced path including the receiver of telephone L6, armature 633, conductor 648, lower winding of relay 646, armature 643, conductor 644 to grounded spring 645, relay 646 actuating. Incidental to relay 646 actuating its armatures 649 and 650 engage make-before-break springs 602 and 604 respectively, and thereby reciprocate the relationship of the windings of relay 601 to conductors 603 and 113 as primarily existing. A telephonic circuit now exists from the calling telephone L to conductors 603 and 113 and from conductor 603, condenser 651, conductor 647 over the traced circuit including the receiver of telephone L6 to conductor 648, condenser 652, to conductor 113.
- Assume that the called party at telephone L6 restores the receiver at the termination of the conversation, the calling subscriber still holding the receiver off the switchhook. Relay 646 will deactuate, restoring the direction of current traversing the receiver of telephone L to that primarily existing. Upon the calling subscriber now replacing the receiver on the switchhook opening the energizing circuit of relay 601, and its dependent relay 606, a circuit can be traced from the winding of release-magnet Re6, armature 655, spring 656 to grounded armature 608, the release magnet operating to restore the shaft carrying wipers 616 to 619 to normal position. Ground being removed from conductor 609 consequent to armature 608 retracting, lineswitch LS, first selector FS and second selector SS will restore in the well known manner, whereupon the concerned circuits and equipments are at normal.
- If, at the time wiper 617 engaged bank contact 626 it found ground potential thereon, due to a connector having access to a multiplied contact thereof being in seized engagement with it, applying a ground to it as was set forth in relation to connector F hereinbefore, a circuit would have been established from grounded contact 626, wiper 617, wiper 622, winding of relay 657, make-before-break spring 621 to the winding of private magnet P6, thus maintaining the private magnet, notwithstanding the retraction of armature 620. Under this condition sideswitch wipers 615 and 622 are not permitted to advance into their third position, so that relay 629 will not actuate. Consequent to the actuation of relay 657, grounded tone source T6 is applied through armature 659 to conductor 648 and over the described path including the receiver of telephone L, conductor 603, upper winding of relay 601 to grounded battery, the tone being audible to the calling subscriber indicative that the line leading to telephone L6 is busy. A locking circuit for relay 657 is established incidental to its actuation from the winding of private magnet P6, spring 621, winding of relay 657, armature 660, armature 661, conductor 644, to grounded spring 645. The tone, and the private magnet is thus maintained until the locking circuit is opened at spring 645, which

can only occur when the switch has been restored to normal by the calling subscriber replacing the receiver on the switchhook, as described.

Inasmuch as features of novelty in connector 5 F reside in the converting relay 662 and in bank contact 625, wiper 616, and the circuits inter-linked therewith, and that these have not been brought into requisition in the described call from telephone L to telephone L6, the functioning of 10 the equipments concerned has been substantially as in well known types of equipments. However, it will appear presently, the connector F operates in a novel manner under certain operative conditions which relate to calls effected wherein a 15 toll selector B cooperates with it, in lieu of a local selector SS as has been described.

With reference to Fig. 15 it will now be seen how a call is extended through the toll switchboard springjack D to called telephone L6. Upon 20 inserting switching plug 501 of switching cord-pair C into springjack D leading over a trunk to toll first selector E, spring 502 applies its ground to conductor 503. In this connection it will be stated that conductors 503 to 506 are in multiple 25 relation to other springjacks similar to D and that there are lamps connected correspondingly to 507 associated with each said springjack so that when the multiplied lamps corresponding to 507 glow due to conductor 503 becoming grounded operators will know that the first selector E 30 is busy by having been seized by some operator having access to it. A circuit can now be traced from the winding of marginal relay 508, make-before-break spring 509 of calling device key d, 35 sleeve conductor 510, conductor 512, spring 513, conductor 504, armature 514 to the winding of relay 515, relay 515 actuating. A circuit can now be traced from grounded armature 516 to the 40 winding of slow releasing relay 517, relay 517 actuating. Grounded armature 518 places a supplemental ground on conductor 503.

The operator will now manipulate calling device key d, whereupon a circuit can be traced from ground through the calling device 520 (which is similar to the calling device in telephone L), spring 521, spring 509, conductor 510, 45 conductor 512, spring 513, armature 514 to the winding of relay 515. Upon the operator manipulating the calling device 520 in accordance with the first digit "1", relay 515 will de-actuate and reactuate one time responsive thereto, whereupon armature 516 closes a circuit from its ground, 50 armature 523, series winding of slow-releasing relay 524, armature 525 to the winding of the vertical magnet V5, the vertical magnet operating one time resultant thereto and raises the shaft carrying wipers 526 to 529 one vertical step into alignment with its first bank level.

At the time relay 524 actuates, coincident with 60 the energization of the vertical magnet V5, its armature 533 applies ground from conductor 503 to make-before-break spring 534, winding of relay 535, armature 536, on the rotary magnet R5 to grounded battery, relay 535 actuating and 65 closes a locking circuit from its upper winding terminal, spring 537 of off-normal set ON5, conductor 538, armature 539, to grounded conductor 503. Off-normal set ON5 operates upon the first off-normal movement of the shaft. Upon the 70 retraction of armature 533 a circuit can be traced from the winding of rotary magnet R5, spring 534, spring 537, conductor 538, armature 539 to grounded conductor 503, the rotary magnet operating and advances wipers 526 to 529 into engagement with bank contacts 541 to 544 respectively.

and incidentally disconnects the battery energizing relay 535 at armature 536, relay 535 deactuating. Armature 539 being now retracted, when armature 536 retracts after the described energizing circuit of the rotary magnet is opened at 80 armature 539 a circuit can be traced from grounded battery armature 536, winding of relay 535, spring 537, conductor 538, winding of relay 546 to grounded conductor 503, relay 546 actuating. The marginal adjustment of relay 535 is 85 such that it will not operatively energize with the winding of relay 546 included with its winding. Relay 546 being actuated, the winding of relay 515 is disassociated and it retracts, followed by the de-actuation of relay 517 in sequence. 90

A circuit can now be traced from conductor 504, armature 514, wiper 527, bank contact 542, conductor 400, armature 401 to the winding of relay 402, relay 402 actuating. Upon relay 402 actuating, a circuit can be traced from the winding of slow-releasing relay 403 to grounded armature 404, relay 403 actuating. Armature 405 engages grounded contact 406 and grounds conductor 407 which is communicated to bank contact 541, wiper 526, armature 550 to conductor 100 503, supplementing the ground thereon received from the spring 502. The telephonic circuit extends from the tip spring 551 of spring-jack D, conductor 505, armature 552, wiper 529, bank contact 544, conductor 553 to winding 408 of repeating coil r, and from the ring spring 554, conductor 506, armature 555, wiper 528, bank contact 543, conductor 556 to winding 409 of repeating coil r. 105

Having in mind that the bank contacts in cooperative relation with selector E are in multiple 110 relation with corresponding bank contacts in cooperative relation with other selectors belonging to the group containing E, and the fact that when armature 550 attracts it applies ground from conductor 503 to wiper 526 and to bank contact 541 115 and its multiples that had the selector B been in a seized condition before the described operation ensued relating to switch E in seizing it, bank contact 541 would have constituted ground potential. Therefore, when wiper 526 encountered bank contact 541 and received ground potential therefrom, it would have applied it to the lower winding terminal of relay 546 in common with the ground received from conductor 503 by way of armature 539. Relay 546 having ground 120 on both of its winding terminals cannot be energized, so when armature 536 retracts following the driving of wipers 526 to 529 into engagement with bank contacts 541 to 544 respectively, an energizing circuit operative to relay 535 will be 125 established from grounded battery, armature 536, winding of relay 535, spring 537 to grounded conductor 538. Armature 539 will again lock the winding of relay 535 to grounded conductor 503 and the rotary magnet R5 will be operatively re-energized over the before described path to conductor 503 and an auxiliary path from conductor 538, armature 550, wiper 526 to grounded bank contact 541 which will cause the rotary magnet to advance the wipers 526 to 529 an additional step into engagement with bank contacts 558 to 561 respectively, the re-actuation of relay 535 and the re-functioning of the rotary magnet occurring to advance the wipers successive rotary steps as long as wiper 526 receives ground to re-establish the energizing circuit of relay 535 following its de-energization incidental to the rotary magnet operating. 130

Continuing from the seizure of selector B by selector E as set forth, upon the operator sending

the second digit "2" relay 402 will de-actuate and re-actuate two times responsive thereto, whereupon armature 412 closes a circuit from its ground, armature 413, armature 414, winding of series slow-releasing relay 415 to the winding of the vertical magnet, V4, the vertical magnet operating two times resultant thereto and raises the shaft carrying wipers 416 to 419, 479 and 483 two vertical steps in alignment with its second bank 5 level. At the time relay 415 actuates, coincident with the energization of the vertical magnet V4, its armature 420 applies ground from conductor 407 to conductor 421, spring 422 of off-normal set ON4 to the shunted winding of relay 425, relay 10 425 actuating. Off-normal set ON4 operates upon the first off-normal movement of the shaft. A locking circuit for relay 425 is established from grounded armature 426, armature 427 on rotary magnet R4, conductor 421, spring 422, to the 15 winding of relay 425. Upon the retraction of armature 420 a circuit can be traced from the winding of the rotary magnet R4, armature 428, armature 420 to grounded conductor 407, the rotary magnet operating and advances wipers 20 416 to 419, 479 and 483 into engagement with bank contacts 430 to 433, 493 and 494, respectively. Upon armature 427 retracting a circuit can be traced from the winding of relay 425, spring 422, conductor 421, armature 427, conductor 445, winding of relay 446 to grounded conductor 407, relay 446 actuating. Relay 425 is 25 marginally adjusted to not operatively energize over a circuit including the winding of relay 446.

Had wiper 418 encountered ground potential 30 on bank contact 432, ground potential received therefrom would be conducted over wiper 418, armature 447, conductor 450, armature 451 to conductor 445, thus maintaining ground potential on both winding terminals of relay 446, and a ground 35 path from the winding of relay 425, spring 422, conductor 421, armature 427 to the ground on conductor 445, operatively energizing relay 425, whereupon the rotary magnet R4 will be caused to 40 operate as before and advance the wipers an additional rotary step; this functioning continuing until wiper 418 fails to receive ground potential 45 from an engaged bank contact.

Having in mind that the bank contacts in co-operative relation with selector B are in multiple relation with corresponding bank contacts in co-operative relation with other selectors belonging to the group containing selector B, it will presently appear that the assumed ground on bank contact 432 would occur whenever a selector 50 belonging to the group containing selector B is in seized relation to its co-operative set of bank contacts.

Consequent to the actuation of relay 446 set forth a circuit is established from grounded armature 412, armature 453, conductor 454, wiper 416, bank contact 430, conductor 455, make-before-break spring 602 to the upper winding of relay 601, no circuit being traceable from the lower winding of relay 601. However, relay 601 is operatively energized over the traced path. Upon the actuation of relay 601 the hereinbefore described actuation of relay 606 ensues, applying ground from armature 608 to conductor 609. A circuit can also be traced from grounded battery, resistance 456, armature 451, conductor 450, armature 447, wiper 418, bank contact 432, conductor 457, winding of relay 662 to grounded conductor 609, relay 662 actuating. At this juncture relay 546 in selector E, relays 446, 402 and

403 of selector B and relays 601, 606 and 662 of connector F are actuated.

Upon the operator sending the third digit "1", relay 601 will be caused to de-actuate and re-actuate one time and cause the connector F to function as hereinbefore described to step its wipers 616 to 619 into alignment with its first bank level. Upon the operator sending the fourth digit "2", relay 601 will be caused to de-actuate and re-actuate two times and cause the connector F to function as hereinbefore described and to step its wipers 616 to 619 into engagement with bank contacts 625 to 628 respectively.

It is assumed that the subscriber upon whose premises telephone L6 is located also has a manual toll loop, such as is shown in Fig. 10, extending from a springjack M on the exchange toll switch-board to an independent telephone T10 on the premises of the said subscriber. It will be further assumed that the toll operator inadvertently or unknowingly called the subscriber's said local number to complete the toll call in place of properly routing it over the said toll loop. Upon the wipers 616 to 619 engaging bank contacts 625 to 628 respectively grounded special tone source 100 S6 will be applied from bank contact 625, wiper 616, armature 665, conductor 666, bank contact 431, wiper 417, armature 460, winding 409 of repeating coil r, conductor 556, over the described path to spring 554 of springjack D, conductor 565 of plug 501, spring 566 of key e, spring 567 of listening key g (now operated) through operator circuit N5, spring 568, spring 569, conductor 570, spring 551 over the described path to winding 408 of the repeating coil r, armature 463, resistance 464 to ground, the said tone being audible to the calling toll operator, and due to its distinctiveness, is indicative that the subscriber called has a manual toll loop as set forth. In this connection, it will be observed that due to the fact that relay 662 is attracted incidental to the connector F being seized by selector B, that the before traced path from grounded ringing current source G6 is open at armature 632, and therefore, under the condition of the connector F being seized by toll selector B the automatic application of ringing current to a seized subscriber's line will not 110 ensue. Under the condition of receiving the stated tone the toll operator may withdraw the plug 501 preparatory to inserting it into springjack M and thereafter depressing the ringing key e and apply the ringing current source G5 in bridge of springs 52 and 53 of springjack M leading to telephone T10 and operate the bridged signal device 54 thereat.

Assuming first that the operator withdraws the plug as referred to in the foregoing paragraph, ground on spring 502 will be removed from conductor 503, however, to no operative result because of conductor 503 receiving the stated supplemental ground by way of armature 405 in selector B. However, spring 513 will open the traced energizing circuit of relay 402, causing it to de-actuate and, in turn, open the traced energizing circuit of relay 601, causing it to de-actuate. The retraction of relay 601 will cause the connector F to be released as hereinbefore described with relation to the call from telephone L to telephone L6. The retraction of relay 402 followed by relay 403 in sequence, will establish an operative circuit from grounded armature 412, armature 413, armature 414, spring 465 to the release magnet Re4, causing the selector B to restore its shaft to normal position. Upon armature 405 retracting the traced energizing circuit for relay 546 will be 130 140 150

opened, whereupon relay 546 will de-actuate, establishing an operative circuit from grounded armature 516, armature 523, winding of relay 524, armature 525, spring 575 to the winding of release magnet Re5, causing selector E to restore its shaft to normal position, whereupon the concerned circuits and equipments are at normal.

Assume now that for some reason, perhaps that the manual toll loop extending to the premises of the called subscriber is busy and the toll operator, therefore, wishes to complete the connection over the seized local line to telephone L6 in lieu of releasing the connection. The line having been seized, but not rung upon, the operator will de-press ringing key e and apply ringing current source G5 in bridge of the traced circuit leading to the lower winding 408 and the upper winding 409 of repeating coil r. The inner terminals of the windings 408 and 409 are open at armature 460, but the relay 466 including condenser 467 is included in a bridged circuit from the outer terminal of the winding 409 by way of armature 468 to the outer terminal of winding 408, therefore, in a bridge of conductors 556 and 553. Relay 466 is operative to the impressed ringing current from source G5 and attracts its armature 470 into engagement with its co-operating grounded contact, applying the ground to the winding of slow-releasing relay 471, causing it to actuate. Armature 447 attracting (after armature 472 attracts), opens the traced energizing circuit of relay 662, whereupon said 662 deactuates. Armature 472 attracting into engagement with its co-operating grounded contact applies ground through wiper 419, bank contact 443, conductor 473 to the winding of relay 675, causing it to actuate. A circuit can now be traced from grounded ringing current source GT6, armature 631, armature 632, armature 633, armature 634, wiper 619, bank contact 628, condenser 642, signal bell 641, bank contact 627, wiper 618, armature 635, armature 636, armature 637, armature 638, resistance 676 to ground battery, the signal bell 641 operating. Upon the operator restoring the key e relay 466 will retract, opening the traced energizing circuit of relay 471, causing relay 662 to re-actuate, followed by relay 675 de-actuating in correspondence with the stated relative adjustments of armatures 447 and 472.

Upon the called subscriber responding, by removing the receiver of telephone L6, a circuit can be traced from the upper winding of relay 475, armature 476, winding 477 of repeating coil r, conductor 478, wiper 479, bank contact 480, conductor 481, armature 637, armature 636, armature 635, wiper 618, bank contact 627, receiver of telephone L6, bank contact 628, wiper 619, armature 634, armature 633, armature 632, conductor 678, bank contact 482, wiper 483, conductor 484, winding 485 of repeating coil r, armature 486, to the lower winding of relay 475, relay 475 actuating. Consequent to relay 475 actuating the traced path including relay 466 is opened. Relay 402 is disassociated and armature 488 applies ground from its co-operating grounded contact through armature 453, conductor 454, wiper 416, bank contact 430, conductor 455, spring 602 to the upper winding of relay 601, maintaining relay 601 actuated. Armature 401 is applied to its working contact and, therefore, applies conductor 400 to the winding of relay 403 in lieu of to the winding of relay 402 normally existing. The winding of relay 402 has such a resistance as will permit current sufficient to operatively energize the included winding of relay 508 to flow, and, therefore,

lamp 570 is grounded through armature 571 up until the time armature 401 attracts, but due to the resistance of the winding of relay 403 being of such value that it restricts the current flow below the operative value of relay 508, the armature 571 retracts and extinguishes lamp 570 upon relay 475 actuating resultant to the called subscriber removing the receiver from the switchhook. It is clear that should the called subscriber replace the receiver on the switchhook, de-energizing relay 475, the primary circuit relations will re-exist and relay 508 will be again operatively energized in series with the winding of relay 402, whereupon lamp 570 will re-glow as a clearing signal.

The telephonic circuit previously traced to the inside terminals of the windings 408 and 409 of repeating coil r is closed through armature 460. The telephonic circuit traced through the called telephone to the inner terminals of windings 477 and 485 of repeating coil r; the said inner terminals being connected by condenser 489, and in view of the windings 409 and 408 being in inductive relation to companion windings 477 and 485 respectively, the toll operator, through the operator circuit N5, is in telephonic relation with the called subscriber through the receiver of telephone L6. It is manifest that upon the armatures 460 and 463 attracting, the special tone derived from tone source S6 is disassociated from the telephonic conductors.

Assume that telephone L6' had been called by sending digits corresponding to telephone number "1211" wherein the last digit "1" will cause wipers 616 to 619 to engage bank contacts 681 to 684 respectively and wherein the telephonic circuit traced to wipers 618 and 619 will include a path through the telephone L6' in a manner corresponding to the inclusion of telephone L6 when engaged with bank contacts 627 and 628 respectively. Wiper 617 will apply ground to the winding of cut-off relay 685 through bank contact 682 in a manner corresponding to the application of ground to the winding of cut-off relay 630 when engaged with bank contact 626. Wiper 616, now engaged with bank contact 681, will derive tone from grounded special source U6 in a manner corresponding to deriving tone from source S6 when engaged with bank contact 625. The tone projected from tone source U6 differs from that projected from tone source S6, the tones being distinctive so as to prompt the toll operator of specific conditions with reference to the respective subscribers L6 and L6'. For example, in the case of tone source U6 it may be indicative that the subscriber is not to be accorded credit, and therefore, no collect toll message shall be completed. It would be equally practicable to have the tone from the source U6 indicative that the subscriber can be reached through an independent toll automatic exchange over an automatic toll loop, or in fact any of many special facts relative to the subscriber. It is manifest that there may be a greater plurality than the two tone sources (S6 and U6) available for interchangeable connection to bank contacts engageable to wiper 616, each indicative of a specific condition or conditions relative to the subscriber.

Assume that at the time the wipers 616 to 619 engaged bank contacts 625 to 628 respectively, under the condition of the connector being controlled by the toll operator, bank contact 626 constituted ground potential indicating, as hereinbefore set forth, that the line leading to tele-

phone L6 is busy. A circuit can be traced as before from grounded contact 626, wiper 617, side-switch wiper 622, winding of relay 657, spring 621 to the winding of the private magnet P6, relay 5 657 actuating, and it and the private magnet being maintained after the retraction of armature 620. Tone source T6 is applied through armature 659, resistance 685', conductor 678, bank contact 482, wiper 483, conductor 484, winding 10 485 of repeating coil r, armature 486 to the lower winding of relay 475. The tone will be induced into winding 408 audible to the toll operator calling, indicative that the called line is busy. Due to armature 661 being attracted, the locking circuit 15 hereinbefore traced to the winding of relay 657 will not be completed, and therefore, the attraction of relay 657 will only endure as long as wiper 617 receives ground from bank contact 626; that is to say, until the line leading to the 20 telephone L6 becomes disengaged. Under this condition, the operator can hold the connection awaiting the disengagement of the called line, whereupon the connector F will seize as before described, due to the fact that when the ground 25 is removed from bank contact 626 the private magnet P6 is deenergized, permitting the side-switch wipers 615 and 622 to advance into their third position, energizing relay 629 and applying busy ground to bank contact 626 and its 30 multiples.

It is manifest that upon receiving the busy tone last assumed that two independent tones will be audible to the calling toll operator. One tone being that derived from tone source S6 and the 35 other being that derived from busy tone source T6. In order for these tones not to be confusing, they are not applied constantly and are so timed in their propagation and duration that they are alternately audible. This expedient is attained 40 through timing the interrupter control segments as by giving them suitable angular position with respect to each other on the shaft driving them. The same method of alternatively applying tone sources which may be successively applied audible 45 to the calling toll operator to index a plurality of specific conditions relative to a subscriber is contemplated under the present invention. For example, the tone applied to a bank contact engageable to wiper 616 may constitute a cycle of 50 tones consisting of a plurality of specific tones, each indicative of a special condition, as that the subscriber called has an automatic toll loop, a manual toll loop, that collect calls are to be completed only upon the subscriber personally recognizing the charge, that if no response is obtained 55 instructions are on file which the operator shall consult as to where the call can be completed, etc.

In view of the foregoing, with relation to the 60 application of tones, it will be understood that the various tone sources of the exchange are so timed and durated that tone sources which may be successively applied will not be operative during the same period, that is, there will be audible 65 and silent periods for the various tones and the said periods intermesh when considered in plurality. It will thus be clearly understood that the toll operator may receive a composite tone, possibly applied from a single composite tone 70 source of predetermined character, which will indicate a plurality of facts relative to the subscriber called.

In carrying out the present invention in commercial exchange systems it is not always practicable to install a manual toll loop from the

premises of the subscribers to the exchange toll switchboard, nor would independent automatic toll switching equipments be installed to which automatic toll loops could be connected. This is having in mind that the subscribers' lines lead into various main branch offices of the exchange, all of which may be remote from the exchange toll switchboard, or from the terminating first selector (corresponding to E) of a toll line equipped for automatic calling.

It is manifest that it is practicable to reserve certain numbers in each hundred-group bank accessible to the connectors, as F, to which exchange toll loops can terminate in a manner corresponding to L6 or L6'. That is, for example, the telephone line leading to telephone T23, may have its telephonic conductors and private normal conductor related to bank terminals accessible to connector F corresponding to the relation of the telephonic conductors and the private normal conductor of the line leading to telephone T6. So, in view of the descriptions relating to the equipments of the line extending to telephone T23 which will be detailed presently, it will be clear that exchange toll loops may be terminated in the same hundred groups as the local exchange lines of the subscribers concerned. Having the exchange toll loops in the same hundred group is particularly advantageous in view of the novel release function of connector F under 100 control of a toll operator when it is seized by a toll selector B, about to be described.

It will be assumed that upon the toll operator (exchange or remote) attaining the bank position containing bank terminals 681 to 684 corresponding to the line leading to telephone L6' a tone is received indicative that the concerned subscriber has an exchange toll loop in the same bank group, and tone is received indicative of the called line being busy. The toll operator will 110 consult the toll loop directory and ascertain the bank position (corresponding to the last two digits of the telephone number) of the said exchange toll loop. That is to say, the telephone number of the said loop.

In order to effect connection with the desired exchange toll loop the operator will send digit "1", whereupon relay 601 will de-actuate and re-actuate one time responsive thereto. Upon armature 607 retracting it will apply its ground through armature 612, conductor 687, armature 688 on relay 657 which is actuated due to the busy condition found, armature 689 on converting relay 662, to the winding of the release magnet Re6, the said release magnet actuating to restore the shaft of connector F to normal position, toll selector B retaining its seizure thereof. The toll operator can now send the last two digits of the telephone number corresponding to the exchange toll loop extending to telephone T23 and cause the connector F to attain its bank position, whereupon it will seize its contacts if the said loop is idle, or apply a tone audible to the calling operator indicative thereof if it is busy, in the manner hereinbefore set forth when the line leading to telephone L6 was assumed busy.

Assume that the line leading to telephone L6' does not test busy when wipers 616 to 619 attain engagement with bank contact 681 to 684 respectively, and therefore relay 657 will not actuate, but that cut-on relay 629 will actuate to effect a seizure, instead. The calling operator discerning the tone indicative of the fact that the called subscriber has an exchange toll loop in the same bank group will refrain from applying signaling

current. Upon sending digit "1", whereupon relay 601 will de-actuate and re-actuate one time and armature 607 will apply its ground through armature 612, conductor 637, armature 613, (in lieu of 688 in the before traced path) armature 689 to the winding of the release magnet Ref. 5 the said release magnet actuating to restore the shaft of connector F to normal position, the toll selector B retaining its seizure thereof. The toll operator can now send the last two digits of the telephone number corresponding to the exchange toll loop extending to telephone T23 and cause wipers of the connector F to attain its bank position, whereupon it will function in accordance 10 with its busy or idle condition as set forth hereinbefore.

It is thus manifest that if the connector F attains a bank position, controlled by a toll operator through a toll selector B, and it there 20 encounters either a busy line from which it is barred, or an idle line which it seizes, dialing digit "1" will restore the connector and maintain the interlinked circuits up to and including the said connector, preparatory to operating the connector as primarily.

It is clear that wipers 616 and 617 may be tied, and the engageable pairs of bank contacts thereof may be tied, without operative change. That is to say, the conductor leading to wiper 30 616 may be changed to wiper 617 and the tone connections to bank contacts 681 and 625 may be changed to bank contacts 682 and 626 respectively.

With reference to Figs. 8, 12, and 16, and also 35 with reference to paragraphs, a, b, c, d, e, f, g, h, i and j, the operation of connector A under various assumed operative conditions will be discussed.

In order not to unduly complicate the drawings, only a portion of the connections are shown 40 relating to the bank contacts co-operating with connector A. Bank J shown in Fig. 8 is a somewhat more complete representation of the bank co-operating with the connector A and it shows one of the multiplied banks K co-operating with 45 a connector of the group containing connector A. Only the first and second bank levels are shown, and only six sets of contacts are shown for each level. In commercial systems the bank would consist, ordinarily, of ten levels of ten sets of 50 bank contacts each and would, therefore normally refer to a hundred lines or a hundred bank positions. Usually ten or more banks are connected in a set with their contacts connected in multiple relation respectively, so that the co-operating connectors each have access to the 55 same leading-out lines at corresponding bank positions.

The connector A is a combination local and toll group-selecting connector which is normally 60 not a group selecting-connector. The group-selecting function depends upon a set-up condition being introduced, depending upon the condition found by one of its wipers when it engages the co-operating bank contact of the bank position called. It will appear presently that the connector A functions differently depending upon whether it is seized by a local selector or by a toll selector.

The exemplified operative condition which will 70 be assumed in relation to connector A contemplates varied classes of service. For example, referring to Fig. 16, bank position 11 is dead. Bank position 12 refers to an isolated local subscriber's exchange line. Bank positions 13, 14, 15 and 16 refer to a group of three lines relating

to a single subscriber, and moreover, the subscriber has an independent manual, (or automatic) toll loop. Bank positions 21 and 22 refer to a group of two local subscriber's line positions relating to an isolated subscriber's line. Bank 80 positions 23 and 24 refer to a group of lines relating to a single subscriber, and moreover, the first line of the group occupying bank position 23 is an exchange toll loop. Bank positions 25 and 26 refer to a group of two local subscriber's 85 line positions relating to an isolated subscriber's line.

It will appear, presently, that if a local subscriber (calling through a local selector) causes 90 the wipers of connector A to attain bank position 12 the connector will function as a non-group-selecting connector. That is, will seize the line thereof and automatically apply ringing current to it, if it is not busy, and if it is busy will apply a tone audible to the calling subscriber,

indicative of the condition. If a local subscriber causes the wipers of connector A to attain bank position 13 it will automatically rotate-off as a group-selecting connector, regardless of its busy or idle state, its wipers attaining bank position 100

14, where it will seize the line thereof, if it is not busy, and if it is busy, it will automatically rotate-off as a group selecting connector, its wipers attaining bank position 15, where it will seize the line thereof if it is not busy, and if it is busy, it

105 will automatically rotate-off as a group-selecting connector, its wipers attaining bank position 16, where it will seize the line thereof if it is not busy, and if it is busy, it will apply a tone audible to the calling subscriber, indicative of the con-

110 dition. If a local subscriber causes the wipers of connector A to attain bank position 21, it will automatically rotate-off as a group-selecting connector, regardless of its busy or idle state, its wipers attaining bank position 22, where it will seize the line thereof if it is not busy, and if it is busy, will apply a busy tone audible to the calling subscriber, indicative of the condition.

If a local subscriber causes the wipers of connector A to attain bank position 23, it will automatically rotate-off as a group-selecting connector, regardless of its busy or idle state, its wipers attaining bank position 24, where it will

115 seize the line thereof if it is not busy, and if it is busy, will apply a busy tone audible to the calling subscriber, indicative of the condition. If a local subscriber causes the wipers of connector A to attain bank position 25 it will automatically rotate-off as a group-selecting connector, regardless of its busy or idle state, its wipers attaining bank position 26, where it will seize the line

120 thereof, if it is not busy, and if it is busy, will apply a busy tone audible to the calling subscriber, indicative of the condition.

If a local subscriber causes the wipers of connector A to attain bank position 27 it will automatically rotate-off as a group-selecting connector, regardless of its busy or idle state, its wipers attaining bank position 28, where it will seize the line

125 thereof, if it is not busy, and if it is busy, will apply a busy tone audible to the calling subscriber, indicative of the condition. If a local subscriber causes the wipers of connector A to attain bank position 29 it will automatically rotate-off as a group-selecting connector, regardless of its busy or idle state, its wipers attaining bank position 30, where it will seize the line

130 thereof, if it is not busy, and if it is busy, will apply a busy tone audible to the calling subscriber, indicative of the condition.

Assume that it is desired to reach the local 135 line leading from the bank contacts occupying bank position 15, this line leading to a specific telephone on the premises of the subscriber or is temporarily connected to such a telephone, perhaps at night or on a holiday. Upon the 140 calling subscriber, calling through a local selector, causing the wipers of connector A to attain bank position 15 it will seize and ring upon the line thereof if it is idle, and if it is busy, will apply a tone audible to the calling subscriber, indicative of the condition. This is to say, if the line is busy it will not function as a group-selecting connector and rotate its wipers into position 16. Thus, where the wipers of the connector A primarily attain an interme-

- 5 diate bank position of a group it will not there-
6 after function as a group selecting connector
7 when controlled through a local selector. How-
8 ever, it will presently appear that where the
9 connector is controlled through a toll selector,
10 the toll operator by sending digit "1" can cause
11 it to thereupon function as a group-selecting
12 connector. Therefore, upon the operative con-
13 dition referred to with respect to calling through
14 local selectors, it will appear that if the specific
15 intermediate line called is busy an alternative
16 line will not be seized, though under the op-
17 erative condition of operating the connector A,
18 controlled through a toll selector, the operation
19 of the said connector by way of hunting for
20 an alternative line of the group if an interme-
21 diate line is called is optional, at the will of
22 the toll operator.
23 It will appear, presently, that if a toll op-
24 erator exchange or remote, calling through a toll
25 selector causes the wipers of connector A to at-
tain bank position 12, the connector A will function
26 as a non-group selecting connector. That
27 is, it will seize the line thereof preparatory to
28 the toll operator causing ringing current to be
29 applied to it at will, if it is not busy, and if it
30 is busy, will apply a tone audible to the calling
31 operator indicative of the condition. If a toll
32 operator causes the wipers of connector A to at-
tain bank position 13, it will seize the line there-
33 of, preparatory to the toll operator causing ringing
34 current to be applied to it at will, if it is not
35 busy, and if it is busy, will apply a tone audible
36 to the calling operator indicative of the condi-
37 tion. Under either condition, that of finding the
38 line occupying the bank position 13 (also ap-
39 pearing in bank position 14) idle or busy, a
40 tone will be applied audible to the calling toll
41 operator that is of such specific nature that it
42 is indicative that the called subscriber has a toll
43 loop which may be manual or automatic, depend-
44 ing on the significance of the tone. If the
45 line occupying bank position 13 is busy, a com-
46 posite tone will be audible to the calling toll
47 operator indicative of the said two conditions,
48 the general nature of the composite tone being
49 as hereinbefore referred to. The calling toll
50 operator at this juncture can either withdraw
51 the switching plug and release the connection in the
52 manner as will appear presently and complete
53 the call to the called subscriber over his inde-
54 pendent toll loop, or the operator can apply
55 ringing current at will to the selected line after
56 it becomes idle and the connector thereupon
57 automatically seizes in the manner as will ap-
58 pear presently. In this connection it will be
59 remembered that the line seized at bank posi-
60 tion 13 is the same line as appears in bank posi-
61 tion 14, therefore, if a busy condition is found
62 at bank position 13 as set forth, a busy condi-
63 tion will also exist on the line should it have
64 been seized through bank position 14.
65 Assume now that when the toll operator causes
66 the wipers of connector A to attain bank posi-
67 tion 13, the busy condition alluded to is found.
68 And further, it will be assumed that the toll
69 operator desires to complete the call over one
70 of the subscriber's local lines. In order to ini-
71 tiate the group-selecting operation of connec-
72 tor A the calling toll operator will send digit
73 "1", whereupon the wipers of connector A will
74 be advanced to bank position 14, and due to
75 the busy condition that will also be found there,
76 will automatically advance the wipers into bank
77 position 15. If the line leading from bank posi-
78 tion 15 is idle the connector will seize, pre-
79 paratory to the toll operator applying ringing
80 current over it at will, and if the line thereof
81 is busy the wipers will be automatically advanced
82 to bank position 16, where the connector A will
83 seize if the line thereof is idle, preparatory to
84 the toll operator applying current to it at will,
85 or if it is busy, to apply a tone audible to the
86 toll operator indicative of the condition.
87 If the line occupying bank position 16 is busy
88 as assumed in the foregoing paragraph, the op-
89 erator can release the shaft of connector A to
90 normal position by sending digit "1". If the
91 connector A is released in the manner provided,
92 the calling toll operator by sending the last two
93 digits of the called number, can cause it to
94 function as before, or by sending two digits re-
95 lating to some other bank position, can cause
96 it to be operated by way of reaching the line lead-
97 ing to the premises of some other wanted sub-
98 scriber also accessible to connector A. This fea-
99 ture is particularly advantageous in that it ob-
100 viates releasing the entire connection if a busy
101 line condition is encountered. Where the call
102 emanates from a remote toll switchboard it ad-
103 mits of the line and connections up to and in-
104 cluding the connector being retained interlinked
105 when releasing the connector, and thus saves the
106 time of operators and toll lines that would neces-
107 sarily have to be occupied in establishing a new
108 connection up to the connector, were it neces-
109 sary to release the entire connection.
110 If the toll operator desires to reach a specific
111 line of the group 13—14—15—16, the line leading
112 from the bank contacts occupying bank position
113 15 for example, and accordingly sends the proper
114 impulses to cause the wipers of connector A to
115 primarily attain that bank position. If the line is
116 idle, the connector will seize, preparatory to the
117 toll operator applying ringing current to it at
118 will, and if it is busy a tone audible to the toll
119 operator will be applied indicative of the condi-
120 tion. Under this condition, that of primarily at-
121 taining an intermediate bank position of a group,
122 the connector will not be automatically adapted to
123 function as a group selecting connector. How-
124 ever, upon the operator sending digit "1" follow-
125 ing the connector primarily attaining the called
126 bank position the connector will thereupon func-
127 tion as a group-selecting connector and seek the
128 first succeeding idle line. This functioning will
129 not depend upon the bank position primarily
130 attained being busy. That is to say, if the opera-
131 tor after ringing upon an idle line fails to get a re-
132 sponse, sending digit "1" will cause the connector
133 to advance its wipers to the first idle line of the
134 group and seize it preparatory to the calling toll
135 operator applying ringing current at will. Of
136 course, if the last line of the group is seized or
137 found busy, the connector will not rotate beyond
138 the group containing the called line thereof by
139 reason of the toll operator sending digit "1" but
140 will, under such condition, restore the shaft to
141 normal position as has been adverted to herein-
142 before.
143 It will also appear, presently, that if a toll op-
144 erator (calling through a toll selector) causes
145 wipers of connector A to attain bank position 21,
146 said connector A will automatically function as
147 a group-selecting connector and rotate its wipers
148 into bank position 22. In this connection it may
149 be stated that neither a local subscriber nor a toll
150 operator can cause connector A to stop its wipers
151 resting upon the bank contacts of bank position
152 21, for reasons as will appear presently. If the 153

line leading from the bank contacts of bank position 22 is idle, the connector A will seize, preparatory to the toll operator applying ringing current over it at will, and if the line thereof is busy, a tone will be applied audible to the toll operator, indicative of the condition. The toll operator can then withdraw the switching plug and release the entire connection, or dial digit "1" and release the connector only as referred to in the foregoing paragraph.

It will also appear, presently, that if the toll operator (calling through a toll selector) causes the wipers of connector A to attain bank position 23, the connector A will function as a non-group-selecting connector. That is, it will seize the line thereof, preparatory to the toll operator causing ringing current to be applied to it at will, if it is not busy, and if it is busy, will apply a tone audible to the toll operator indicative of the condition. Under either condition, that of finding the line occupying bank position 23 idle or busy, a tone will be applied audible to the toll operator, that is of such specific nature it will be indicative that the called line is an exchange toll loop. Of course, if the exchange toll loop occupying bank position 23 is busy, a composite tone will be audible to the calling toll operator, indicative of the said two conditions, the general nature of the composite tone being as hereinbefore adverted to. The toll operator at this juncture can either withdraw the switching plug and release the connection in the manner as will appear presently, or the toll operator can send digit "1" and cause the connector to function in group selection and automatically rotate its wipers into engagement with the bank contacts of the line leading to bank position 24, whereupon if the line occupying bank position 24 is idle the connector will seize preparatory to the toll operator applying ringing current to it at will, and if it is busy, will apply a tone audible to the calling toll operator indicative of the condition, whereupon the toll operator can release the connection, or release the connector only as adverted to in the foregoing paragraph.

Assume now that when the toll operator caused the wipers of connector A to attain bank position 23, the line leading from the bank terminals thereof was idle, and that therefore, no busy tone was applied audible to the toll operator. However, a tone indicative of the specific fact that the line occupying position 23 is an exchange toll loop will be applied audible to the toll operator. The toll operator can, at will, apply ringing current over the said exchange toll loop. Of course, if the connection is desired completed over a local exchange line instead of the exchange toll loop the operator can upon sending digit "1" cause the connector to advance its wipers into bank position 24 where it will seize the bank contacts of the local line leading therefrom, if idle, as referred to hereinbefore and, if busy, a tone will be applied audible to the toll operator indicative of the condition.

The connections of the line leading to bank positions 25 and 26 correspond to the connections referred to in relation to bank positions 21 and 22 respectively and, therefore, the functioning of connector A will be the same with relation to bank positions 25 and 26 as has been referred to with relation to bank positions 21 and 22 respectively.

Having in mind that the size of the groups can be varied from those indicated, and the fact that in comprehensive commercial systems there would

be a greater plurality of groups and that the specific tones referred to can be increased in number and character to index further specific conditions appertaining to the subscriber corresponding to the group attained, the detailed operation of connector A and its co-operating switches will be discussed.

Assume a call from telephone L to telephone L12, the telephone number of which is "1112". Upon the calling subscriber at telephone L removing the receiver to initiate the call the lineswitch LS will function as hereinbefore set forth and seize first selector FS. Upon the calling subscriber manipulating the calling device 102 in accordance with the first digit "1", first selector FS will function as hereinbefore set forth and, seize second selector SS. Upon the calling subscriber sending the second digit "1" selector SS will function in a manner as hereinbefore set forth, however, in this instance, rotating-in on its first bank level and seizing the first idle trunk leading to a connector, which in this instance, will be assumed as the trunk consisting of conductors 121 to 123 leading to connector A. A circuit can now be traced from the upper winding of relay 201, make-before-break spring 202, conductor 122, wiper 101, over the before-described circuit including the receiver of telephone L to wiper 112, conductor 123, make-before-break spring 203 to the lower winding of relay 201, relay 201 actuating. A circuit can now be traced from the winding of slow-releasing relay 204 to grounded armature 205, relay 204 actuating. Armature 206 applies its ground to conductor 207, conductor 121, wiper 114, and over the before traced circuit to the winding of relay 119, maintaining the lineswitch LS, the first selector FS, and the second selector SS as hereinbefore described. Upon the calling subscriber sending the third digit "1", relay 201 will de-actuate and re-actuate one time responsive thereto, whereupon armature 205 applies ground through armature 208, series winding of slow-releasing relay 209, winding of the vertical magnet V2, side-switch wiper 210 to grounded battery, relay 209 actuating and the vertical magnet V2 operating to step wipers 212 to 215 into alignment with the first bank level. At the time relay 209 actuates its grounded armature 216 closes an energizing circuit from the lower winding of relay 217, relay 217 actuating, however, to no operative purpose at this juncture. The object of relay 217 will appear presently. Grounded armature 218 closes an energizing circuit from the inner winding of the private magnet P2, causing it to operate preparatory to permitting the sideswitch wipers 210 and 219 to advance into their second position upon its de-energization. Upon the retraction of armature 218, the period of relay 209 following the re-attraction of armature 205, the private magnet P2 de-energizes, permitting the sideswitch wipers 210 and 219 to advance into their second position. Upon the calling subscriber sending the fourth digit "2" relay 201 will de-actuate and re-actuate two times responsive thereto, whereupon armature 205 will apply two ground impulses through armature 208, winding of relay 209, armature 221, winding of the rotary magnet R2, wiper 210 to grounded battery, relay 209 actuating and sustaining over the lapse between the impulses, causing the private magnet P2 to actuate preparatory to permitting the sideswitch wipers to advance into their third position upon its de-energization, and the rotary magnet R2 operating to drive the wipers 212 to 215 two rotary steps into engagement with bank 150

contacts 222 to 225 respectively, occupying bank position 12 hereinbefore referred to.

Assume that the line leading to called telephone L12 is idle and that, therefore, bank contact 223 does not constitute ground potential. Upon the retraction of armature 218 the period of relay 209 following the re-attraction of armature 205 the last time, the energizing circuit of the private magnet P2 is opened and its armature retracts and permits the sideswitch wipers 210 and 219 to advance into their third position. A circuit can now be traced from ground, wiper 219, conductor 226, winding of relay 227, wiper 210 to grounded battery, relay 227 actuating. Ground from conductor 226 is applied through wiper 213 to bank contact 223 and its multiples to guard the called line against intrusion, and also operatively energizes cut-off relay 301 over conductor 303 to disassociate the telephonic conductors from affecting attachments. Armature 216 does not retract, due to the characteristic of its relay 209, until an interval has elapsed after the armature 228 on the rotary magnet R2 has retracted and closed a path between the winding terminals of the upper-winding of relay 217. The upper winding of relay 217 is thus closed upon itself before its lower winding is de-energized due to the retraction of armature 216 and, therefore, the relay 217 has a slow-releasing characteristic under the condition, the object of which will appear presently.

Upon relay 227 actuating, a circuit can be traced from grounded interrupted generator source G2, armature 229, armature 230, armature 231, conductor 232, armature 233, wiper 215, bank contact 225, conductor 234, signal bell 305, condenser 306, conductor 307, bank contact 224, wiper 214, armature 235, armature 237, armature 238, armature 239, inner winding of relay 240 to grounded battery, the signal bell 305 operating. The characteristic of relay 240 is such that it will not be operatively energized with the condenser 306 included in its energizing circuit. However, upon a conductive path being closed between conductors 234 and 307 including the receiver of telephone L12 off the switchhook, the relay 240 will be operatively energized. The latter condition will ensue upon the called party responding, whereupon a circuit can be traced from grounded spring 241 of the off-normal spring set ON2 (which operated upon the first vertical movement of the shaft carrying wipers 212 to 215), conductor 242, armature 243, outer winding of relay 240 to grounded battery, locking relay 240. A circuit can also be traced following the attraction of armature 243, from grounded spring 241, conductor 242, armature 243, conductor 224, lower winding of relay 245, conductor 246, armature 231, armature 233, wiper 215, bank contact 225, over the traced circuit including the receiver of telephone L12, bank contact 224, wiper 214, armature 235, armature 237, conductor 247, to the upper winding of relay 245, relay 245 actuating. Upon armatures 248 and 249 of relay 245 attracting into engagement with their co-operating make-before-springs 202 and 203 respectively, the relation of the windings of relay 201 described with respect to conductors 122 and 123 will be reciprocated, and therefore, the current traversing the receiver of the calling telephone L will be reversed in direction. The latter function has no operative purpose here, but may serve to effect supervision to certain of the lines accessible to connector A.

The telephonic circuit traced from the calling telephone L to conductors 122 and 123 and from

the called telephone L12 to conductors 247 and 246 are joined by condensers 249 and 250 respectively, so that the calling subscriber at telephone L is in telephonic relation with the called subscriber at telephone L12.

80

Assume that bank contact 223 constituted ground potential at the time wiper 213 engaged it, and after armature 251 on relay 217 retracts its period after the retraction of armature 216, having in mind the retracted condition of armature 228 on the rotary magnet R2. Under this condition the line leading to telephone L12 would be busy either because of a companion connector of the group containing A is in seized relation to it or because a call has been initiated from telephone L12, the operation of the lineswitch containing relay 301 of the line leading to telephone L12 in applying ground to the conductor 303 leading to the bank contact 223 being well known. A circuit can now be traced from grounded bank contact 223, wiper 213, conductor 226, wiper 219 in second position, armature 252, retardation coil r2, conductor 253, spring 254, armature 251, winding of relay 255, wiper 210 to grounded battery, relay 255 actuating. A locking circuit for relay 255 can be traced from its lower winding terminal, armature 251, spring 254, armature 256, armature 257, make-before-break spring 258, conductor 242 to grounded spring 241. This locking circuit will endure until the ground is opened at spring 241 or at armature 257. Grounded tone source T2 will be applied to armature 259, conductor 246, and over the hereinbefore traced path including the receiver of telephone L to grounded battery by way of the upper winding of relay 201, audible to the calling subscriber, and due to the character of the tone, indexes the condition. Referring to Fig. 8 it will be noted that bank contacts 222 and 223 are tied together by way of conductor 801, tie-conductor 802, and conductor 803 so that when bank contact 223 constitutes ground potential bank contact 222 will also constitute ground potential. Therefore, when wiper 212 engages bank contact 222 and after armature 260 retracts, a path can be traced from grounded bank contact 222, wiper 212, conductor 261, armature 260, conductor 253, spring 254, armature 251, conductor 262, armature 264, lower winding of relay 263, to ground, no current traversing the circuit. Upon the retraction of armature 251 the traced ground paths from bank contact 222 to conductor 253 and from bank contact 223 to conductor 253 will operate in parallel, effective to energize relay 255 by way of armature 251.

90

95

100

105

110

115

120

125

130

135

140

145

Going back to the assumed condition wherein wiper 213 first engaged bank contact 223 when it did not constitute ground potential but due to the inclusion of the winding of relay 301 constituted battery potential in lieu thereof. Under this condition an energizing circuit can be traced from the winding of relay 301, conductor 303, bank contact 223, wiper 213, conductor 226, wiper 219, armature 252, retardation coil r2, conductor 253, spring 254, armature 251, conductor 262, armature 264, lower winding of relay 263 to ground. Armature 252 will not be attracted from its resting contact due to the marginal adjustment of relay 263 and, therefore, will not engage its working contact due to the fact that this energizing current traversing its lower winding is not sufficiently strong to operatively energize it, due to its said marginal adjustment.

Assume that the conversation is terminated and that the called party at telephone L12 replaces the receiver on the switchhook. Relay 245 will

150

de-actuate. Upon the calling subscriber at telephone L replacing the receiver on the switchhook relay 201 will de-actuate followed by dependent relay 204 in sequence. A circuit can now be traced from grounded armature 206, off-normal spring 265, to the winding of release magnet R_{c2}, the release magnet operating to restore the shaft to normal position. Armature 206 retracting removes ground from conductor 121 and its attachments, so that the concerned circuits and equipments are now normal.

Assuming a call from telephone L to telephone L₂₄, the group number of which is "1123". The functioning of the apparatus consequent to the calling subscriber removing the receiver from the switchhook of telephone L up to, and including the sending of the first two digits "11" whereupon the connector A is seized and relays 201 and 204 thereof are caused to actuate and conductor 121 is grounded by armature 206 is as hereinbefore described in relation to the call to telephone L₁₂. Upon the calling subscriber sending the third digit "2", relay 201 will de-actuate and re-actuate two times responsive thereto, whereupon armature 205 applies two ground impulses through armature 208, winding of relay 209, winding of the vertical magnet V₂, sideswitch wiper 210 to grounded battery, relay 209 actuating and sustaining over the two impulses and the vertical magnet V₂ operates to step wipers 212 to 215 into alignment with the second bank level. The operation of the private magnet P₂ consequent to armature 218 attracting and retracting is as hereinbefore described, so that following the retraction of armature 218 after the wipers are in alignment with the second bank level, the sideswitch wipers 210 and 219 are permitted to advance into their second position. Upon the calling subscriber sending the fourth digit "3", relay 201 will de-actuate and re-actuate three times responsive thereto, whereupon armature 205 applies two ground impulses through armature 208, winding of relay 209, armature 221, winding of rotary magnet R₂, wiper 210 to grounded battery, relay 209 actuating and sustaining over the three impulses and the rotary magnet R₂ operates to drive wipers 212 to 215 three rotary steps into engagement with bank contacts 266 to 269 respectively, occupying bank position 23 hereinbefore referred to. Upon the retraction of armature 260, and before the retraction of armature 251, a circuit can be traced from grounded battery, winding 270, of tone induction coil TL₂, conductor 271, bank contact 266, wiper 212, conductor 261, armature 260, spring 254, armature 251, conductor 262, armature 264, lower winding of relay 263 to ground, relay 263 actuating. The armature 260 to relay 209 being adjusted to engage its resting contact upon retracting before armature 218 disengages its working contact insures that the sideswitch wipers will be restrained from advancing into their third position by reason of armature 272 applying its ground to the outer winding of private magnet P₂ to maintain it, before it has de-actuated by reason of the inner winding thereof de-energizing consequent to armature 218 retracting. A circuit can now be traced from armature 218, armature 273, armature 274, on the private magnet, armature 275, armature 221, winding of the rotary magnet R₂, wiper 210 to grounded battery, the rotary magnet actuating and advancing wipers 212 to 215 into engagement with bank contacts 276 to 279 respectively, occupying bank position 24, relay 263 de-actuating provided bank contact 277 does not constitute

ground potential, as will appear. Assume for the present that bank contact 277 does not constitute ground potential and that relay 263 therefore retracts. Upon armature 272 retracting the private magnet P₂ de-actuates, permitting the sideswitch wipers 210 and 219 to advance into their third position. A circuit can now be traced from ground, wiper 219, conductor 226, winding of relay 227, wiper 210, to grounded battery, relay 227 actuating. Ground from conductor 226 is also applied through wiper 213, bank contact 277, conductor 280 to the winding of relay 302 of the line-switch associated with the line leading to telephone L₂₄, disassociating affecting attachments from the telephonic conductors of the said line.

Assume that when the rotary magnet R₂ advanced the wipers 212 to 215 into engagement with bank contacts 276 to 279 respectively wiper 213 encountered ground potential on bank contact 277 due to the line leading to telephone L₂₄ being busy and, therefore, causing conductor 280 and its multiplied bank contacts to constitute ground potential in a manner as referred to hereintofore with respect to conductor 303. Referring to Fig. 8 it will be noted that bank contacts 276 and 277 are electrically tied over conductor 280, tie conductor 804, conductor 805, so that when bank contact 277 constitutes ground potential, bank contact 276 will also constitute ground potential. A circuit can be traced from grounded bank contact 277, wiper 213, conductor 226, wiper 219, make-before-break spring 281, to the outer winding of the private magnet P₂, maintaining it actuated and thus restraining the sideswitch wipers 210 and 219 from advancing into their third position. A circuit can also be traced from ground, sideswitch wiper 219, armature 252, retardation coil r₂, conductor 253, spring 254, armature 251, winding of relay 255, wiper 210 to grounded battery, relay 255 actuating. A parallel circuit can be traced from grounded conductor 280, tie conductor 804, conductor 805, bank contact 276, wiper 212, conductor 261, armature 260 to conductor 253. Upon armature 256 engaging spring 254 the hereinbefore described locking circuit for relay 255 is established and the busy tone source T₂ is applied audible to the calling subscriber as hereinbefore set forth. It is now clear that notwithstanding the subscriber caused the connector A to operate, causing its wipers 212 to 215 to primarily attain bank position 23 which is the bank position of the first line of the group belonging to the subscriber having local telephone L₂₄, that it was automatically operated to advance the said wipers to attain bank position 24, the bank contacts belonging to which concern the line to telephone L₂₄. From previous statements it is recalled that the line occupying bank position 23 is an exchange toll loop and, therefore, is not intended to be seizable to connector A when the said connector is operated through a local selector.

A distinctive feature of bank position 23 from bank position 24 is that bank contact 266 constitutes grounded battery potential of sufficient voltage to operatively energize relay 263 when wiper 212 engages said bank contact 266 and armature 260 has retracted following the last control impulse, while bank contact 276 does not constitute battery potential of the said operative voltage applied to bank contact 266. So it is manifest that when wiper 212 is resting upon a bank contact, constituting battery potential of sufficient voltage to operatively energize relay 263 following the last control im-

pulse applied to the connector, the connector will be caused to automatically advance its wipers one rotary position. Moreover, as will appear presently, the connector is thereby converted into a group-selecting connector and will continue to rotate until wiper 212 encounters a bank contact constituting ground potential, unless its companion wiper 213 fails to receive ground from an engaged bank contact, when the switch will thereupon cease functioning as a group-selecting connector and forthwith seize the set of bank contacts then engaged.

Going back to the condition which ensued when relay 227 actuated while wipers 212 to 215 were in engagement with bank contacts 276 to 279 respectively. The circuit condition from calling telephone L to wipers 214 and 215 is the same as when telephone L12 was called and wipers 212 to 215 engaged bank contacts 222 to 225 respectively, and relay 227 actuated. Grounded interrupted ringing current can be traced from source G2 over the hereinbefore described path to wiper 215, bank contact 279, conductor 310, condenser 312, signal bell 313, conductor 314, bank contact 278, wiper 214, and over the hereinbefore described path through the inner winding of relay 240 to grounded battery, relay 240 not being operatively energized. However, the signal bell 313 will operate and the called subscriber will respond by removing the receiver from the switchhook of telephone L24, whereupon the same stated functioning of connector A will ensue as described in relation to the call from telephone L to telephone L12 where- in the receiver of telephone L12 was removed from the switchhook in responding. The release of the connector will not be redetailed since it will function as before clearly described when the receiver of telephone L was restored upon terminating the conversation with called telephone L12.

Referring to Figs. 12 and 8 it will be assumed that a call is made from telephone L to the subscriber's premises having a group of three local lines occupying bank positions 14, 15 and 16 and also has a manual (or automatic) toll loop in addition. Since the subscriber has reserved to him bank positions 13, 14, 15 and 16, his telephone group number being "1113", referring to bank position 13, which in view of the statement above is the first bank position of the group reserved to him though it will be borne in mind that the local lines refer to bank positions 14, 15 and 16. The calling subscriber at telephone L will initiate the call and attain the seizure of connector A as hereinbefore set forth upon sending the first two digits "11". Upon sending the third "1" the connector A will function as hereinbefore described when it stepped its wipers into alignment with the first level responsive to the third digit "1". Upon the last digit "3" being sent, the connector A will operate as hereinbefore described when the last digit sent was "2" in attaining bank position 12, however, in this instance it is caused to rotate three steps under control of the calling subscriber, the wipers 212 to 215 stopping on bank contacts 282 to 285 respectively.

In this connection it is to be understood that conductors 810 to 814, 303 and 816 lead to the cut-off relays in lineswitches respectively as represented by relay 301 and its attached conductor 303, for example, and that therefore, battery potential through a line cut-off relay exists on bank contacts 285 to 288, the relays and line-

switches not being shown to avoid unduly involving the drawings. The lines to the subscriber concerned are thus arranged for completing calls outgoing from the subscriber's premises though it will appear that no special, corresponding line is connected between the bank contacts occupying bank position 13 and the premises of the subscriber, and that, therefore, the conductor 814 (also 810) may be disassociated from the cut-off relay of the lineswitch provided for the bank contacts corresponding to bank position 13, in fact, the lineswitch corresponding to bank position 13 (also, 21) is disassociated.

In this connection it may be stated that in equipping commercial installations all bank positions may be wired contemplating that in and out service would be rendered over the line corresponding to each bank position, and that the bank positions would be organized in groups referring to various subscribers depending upon the traffic requirements of the subscribers, perhaps leaving vacancies or dead bank positions in a group of bank positions set apart for the subscribers with due anticipation of prospective requirements in the way of additional lines. So that where a line is not actually in service the lineswitches may be assumed as dis-associated and the conductors relating thereto open. It will appear presently that where a subscriber has a group of lines, or an isolated line accessible to a connector as A, a blank position, being the first position of the group, may be reserved in anticipation that the subscriber will at some time require an exchange toll loop, the exchange toll loop occupying the first bank position of a group and, therefore, the telephone number of the subscriber as appearing in the general telephone directory will refer to the bank position of the anticipated exchange toll loop. It is manifest in view of this, that a call to the group from any source will be primarily directed to the bank position corresponding to the anticipated exchange toll loop. Thus, it will further appear that if a bank position of a subscriber group is reserved in contemplation of an exchange loop being installed, or in fact a manual toll loop or an automatic toll loop or any special condition that might affect the service or the status of the subscriber with respect to calls emanating from lines reached through toll selectors, calls from local telephones reached through local selectors, as well as from toll operators reached through toll selectors are directed to the first bank position of any such group. The connector for completing the connection from a local selector will be caused to automatically ignore the bank position not constituting a local line and will function as a group-selecting connector in automatically rotating into testing engagement with the first and successive local lines of the group, seizing the local line, or if there be a plurality, the first idle line of the group, applying a busy tone, audible to the calling subscriber if no line is found idle, when the connector is controlled from a local telephone.

Going back to the status wherein wipers 212 to 215 were rotated into engagement with bank contacts 282 to 285 respectively, occupying bank position 13, armature 260 having retracted. Wiper 213 will not receive battery potential if the line cut-off relay has been dis-associated as adverted to, however, if the line cut-off relay has not been dis-associated and it receives battery potential, it will not be to any operative result due to the marginal characteristic of relay 263 described hereinbefore. However, battery po-

tential and a superposed tone will be conducted through the secondary winding 289 of special tone source TT2, conductor 290, bank contact 282, wiper 212, armature 260, spring 254, armature 251, conductor 262, armature 264, lower winding of relay 263 to ground, relay 263 actuating. Assuming that bank contact 283 does not constitute ground potential, no ground will be applied over conductor 226 to armature 252 which will

- 5 10 lock relay 263 actuated by way of its upper winding. However, a circuit can be traced from armature 218, armature 273, armature 274, armature 275, armature 221, winding of rotary magnet R2, sideswitch wiper 210 to grounded battery, the 15 sideswitch wipers 210 and 219 having been restrained from advancing into their second position, due to grounded armature 272 having been applied to the outer winding of the private magnet P2, maintaining it actuated as hereinbefore described. The last described circuit energizing the rotary magnet R2 causes the wipers 212 to 215 to be advanced a rotary step into engagement with the bank contacts 291, 292, 293 and 286 respectively, occupying bank position 14. Armature 228 attracting causes relay 217 to deactivate forthwith.

Assume first that the local line of the group leading to telephone L14 is idle and, therefore, bank contact 292 does not constitute ground potential, bank contact 291 being unconnected and, therefore, has no operative purpose. Wiper 213 not finding ground potential, relay 263 will not be maintained energized and it will de-actuate, whereupon the private magnet P2 will de-actuate, 30 permitting the sideswitch wipers 210 and 219 to advance into their third position. A circuit can now be traced from ground, wiper 219, conductor 226, winding of relay 227, wiper 210 to grounded battery, relay 227 actuating. Ground can also 35 be traced from conductor 226, wiper 213, bank contact 292 and its multiples, guarding the line leading from bank position 14 against intrusion. The line leading to telephone L14 will be signalled upon automatically as has been hereinbefore described with reference to the seizure of bank contacts 222 to 225 corresponding to telephone L12 and, therefore, need not be detailed.

It will now be assumed that the line leading to telephone L14 is busy, and that, therefore, bank contact 292 constitutes ground potential when wiper 213 first engages it in automatically rotating from bank position 13. Having in mind that relay 263 was caused to actuate due to wiper 212 finding battery potential on bank contact 282, and that its armature 252 is therefore attracted when wiper 213 engages grounded bank contact 292, a circuit can be traced from said grounded bank contact 292, wiper 213, conductor 226, wiper 219, armature 252 to the upper winding of relay 263, maintaining it locked. Grounded armature 272 maintains the private magnet P2 energized, restraining the sideswitch wipers 210 and 219 from advancing into their second position. A circuit can now be traced 45 from grounded armature 218, armature 273, armature 274, armature 275, armature 221, winding of rotary magnet R2, wiper 210 to grounded battery, the rotary magnet again operating to advance wipers 212 to 215 into engagement with bank contacts 294, 295, 296 and 287 respectively. Incidental to the rotary magnet R2 actuating a circuit can be traced from the winding of relay 296', armature 297 to its co-operating grounded contact, relay 296' actuating to open the traced energizing circuit of the rotary mag-

net R2, causing it to deactivate followed by relay 296' preparatory to being re-energized to advance the wipers 212 to 215 into engagement with bank contacts, 298, 299, 201' and 288 respectively.

Assuming now that bank contact 295 does not constitute ground potential when engaged by wiper 213 (but may derive battery potential over conductor 812) the locking circuit for relay 263 traced will be opened and it will de-actuate, 80 whereupon the private magnet P2 will de-actuate permitting the sideswitch wipers 210 and 219 to advance into their third position and establish the hereinbefore described circuit from ground, wiper 219, conductor 226, winding of relay 227, wiper 210 to grounded battery, relay 227 actuating. The signal bell at telephone L15 will now be automatically rung in the manner hereinbefore described with reference to telephone L12 being called. 90

It will now be assumed that bank contact 295 constitutes ground potential when wiper 213 engages it and, therefore, the traced ground path from the upper winding of relay 263 to wiper 213 is maintained. Thus, when the rotary magnet R2 detracts after driving wipers 212 to 215 into engagement with bank contacts 294 to 296 and 287 respectively and relay 296' de-actuates upon armature 297 on the rotary magnet R2 retracting, the path from grounded armature 218, 105 armature 273 and including the winding of the rotary magnet R2 to grounded battery is re-established, causing the rotary magnet to drive the wipers 212 to 215 into engagement with bank contacts 298, 299, 201' and 288 respectively. If 110 bank contact 299 does not constitute ground potential relay 263 will de-actuate, followed by private magnet P2, whereupon relay 227 will actuate and the line leading to telephone L16 will be signalled upon in the manner as described in 115 connection with the calling of telephone L12.

Assuming, however, that bank contact 299 constitutes ground potential, and that therefore, bank contact 298 also constitutes ground potential by reason of the said bank contacts being 120 electrically tied by way of conductor 820, tie conductor 821, and conductor 822, a circuit can be traced from grounded bank contact 298, wiper 212, conductor 261, armature 260, spring 254, armature 251, winding of relay 255, wiper 210 to grounded battery, relay 255 actuating applying a tone from tone source T2 audible to the calling subscriber indicative that all the local lines of the group are busy. Relay 255 is locked, dependent upon grounded spring 241 and armature 257 as before described, so the tone will be applied audible to the calling subscriber until connector A is restored to normal. At the time relay 255 actuated and locked relay 263 was already actuated and locked, dependent upon 130 ground being maintained on wiper 213. However, since armature 221 on relay 255 is attracted, the rotary magnet R2 is incapacitated against further operation, regardless of the condition of relay 263. That is to say, if while the calling 140 subscriber is still holding the connector A and receiving the busy tone the line leading to telephone L16 becomes disengaged and relay 263 thereby becomes unlocked there will be no operative effect therefrom. However, the tone will 145 be maintained audible to the calling subscriber, because relay 255 is locked dependent upon spring 241 and armature 257. Further, when relay 255 actuates and locks, the ground on armature 256 is applied to spring 202' and to the in- 150

ner winding of the private magnet P2, maintaining it actuated dependent upon spring 241 and armature 257. It is thus clear that if a calling subscriber receives a busy tone, the connector 5 A seized by a local selector, is incapacitated against seizing a line its wipers may be in engagement with the bank contacts of which, regardless of the fact the busy condition of the selected line may have terminated. However 10 it will appear presently, that where the connector A is seized by a toll selector (under control of a toll operator) this functioning of the connector A is altered and that under certain conditions, as will appear, the connector A cannot only 15 seize a line it has selected upon it becoming idle, but the said connector is capacitated to be controlled in various ways by the calling toll operator.

Under the assumed condition wherein the connector A encounters a busy group of lines, its 20 release is dependent upon the calling subscriber replacing the receiver on the switchhook, whereupon relay 201 will de-actuate, followed by relay 204 in sequence, and whereupon a circuit is 25 established from grounded armature 206, spring 265, to the winding of the release magnet Re2; the release magnet actuating to restore the shaft of the connector to normal and unlock relay 255 and the private magnet P2, and also the relay 265, if it has not already previously de-actuated because of the ground having been removed from bank contact due to the selected line 30 becoming idle as set forth hereinbefore.

It will now be assumed that the calling subscriber at telephone L desires to effect a connection with local telephone L15, and not to any other telephone of the subscriber's group concerned. The operation will be the same as hereinbefore described wherein telephone number "1113" was 35 called, only in the present instance the last digit will be "5", indexing bank position 15, containing the desired telephone line, corresponding to bank contacts 294 to 296, and 287 respectively. It will be noted that bank contact 294 is unconnected 40 and that, therefore, when armature 260 retracts following the last impulse to the rotary magnet R2 no circuit including the lower winding of relay 263 will be established, and therefore, in view of previous descriptions no automatic rotary movement of the shaft of connector A will be 45 initiated.

If the bank contact 295 constitutes ground potential, this ground potential will be conducted to wiper 213, conductor 226, wiper 219, spring 281 50 to the outer winding of the private magnet P2, maintaining it energized and this ground will be also communicated to armature 252, retardation coil r2, spring 254, armature 251, winding of relay 255, wiper 210 to grounded battery, relay 255 actuating and locking by way of armature 256, 55 armature 257, spring 258, conductor 242 to grounded spring 241, and tone will be applied from tone source T2, armature 259, to conductor 246 and over the described path including the receiver of telephone L as has been described hereinbefore, indicative that the called line is busy. Due to the relay 255 being maintained locked, dependent upon grounded spring 241 and armature 257, and also that the inner winding of the private 60 magnet P2 is maintained energized to contact 202', dependent upon grounded spring 241, and armature 257, the connector cannot seize nor advance its wipers. Therefore, no alternative line can be reached by any automatic process 65 initiated from a set up condition in the connector,

or by reason of the called line being found busy.

It will be clear that an important difference in the condition set up in connector A upon the armature 260 retracting following the last impulse relating to the called number in the present exampled case over that wherein telephone L14 was called, is that no battery potential was found by wiper 212, and therefore, the connector A was not capacitated to function as a group-selecting connector through the offices of relay 263. That is to say, if the wiper 212 does not find battery potential following the last impulse constituting the called number the connector A will not be capacitated for group selection.

It will now be assumed that a call is made from telephone L to the subscriber's premises having an isolated local line leading to terminals in bank position 22. The subscriber has reserved to him bank positions 21 and 22, his telephone group number being "1121", referring to bank position 21, which is nominally the first bank position of the group, though it will appear that connector A cannot rest its wipers on the bank contacts corresponding to the said position under any condition, due to the fact that bank contact 204' constitutes battery potential of sufficient voltage to be operative to relay 263 with resistance 205' included in the energizing circuit, as will also appear, presently. Bank position 21, therefore, has no service purpose, it being a dead or reserved 100 bank position, set apart perhaps, in anticipation that the concerned subscriber will have some special condition, such as a manual toll loop, automatic toll loop, exchange toll loop or other special condition or service peculiarity wherein it 105 will be desired to disconnect the conductor 206' leading to the high-voltage battery B2 from bank contact 204' and its multiples and substitute therefore a conductor leading from said 204' and its multiples to conductor 271, or conductor 290 110 115 for example.

In this connection it may be stated that all groups containing local lines only and where no special information is to be imparted to a calling toll operator, will have the bank contacts of the 120 first bank position thereof engageable to wiper 212 connected to battery source B2. That is to say, the first bank position of a group of lines, all of which are local lines, has the first bank position dead, as in the case of bank position 21. 125 This is so the connector will function in group selection and rotate off the first set of bank contacts of a group and test if the first or pilot line of the group is called through either local or toll selectors.

The calling subscriber at telephone L will initiate the call and attain the seizure of connector A as hereinbefore set forth upon sending the first two digits "11". Upon sending the third digit "2" the connector will function as hereinbefore described when it stepped its wipers into alignment with the second bank level, responsive to the third digit "2" being sent by the calling subscriber at telephone L. Upon the last digit "1" being sent, the connector will operate as hereinbefore described, its wipers attaining bank position 21. Upon the retraction of armature 260 a circuit can be traced from high-voltage battery source B2, bank contact 204', wiper 212, conductor 261, armature 260, spring 254, armature 251, conductor 262, armature 264, lower winding of relay 263 to ground, relay 263 actuating, advancing the wipers 212 to 215 into engagement with bank contacts 208' to 211' respectively. The bank contact 208' being tied to bank contact 209' by way of 145 150

conductor 825 tie conductor 826, conductor 827, bank contact 208' will constitute ground potential whenever bank contact 209' constitutes ground potential.

- 6 Assume that the line leading to telephone L22 occupying bank position 22 is idle, and therefore, bank contacts 208' and 209' do not constitute ground potential and, therefore, wiper 213 does not become grounded wherein it will maintain 80
10 the locking circuit for the upper winding of relay 263 and the energizing circuit of the private magnet in a manner as hereinbefore described, whereupon relay 263 will de-actuate consequent upon the wiper 212 rotating from bank contact 15 85
15 204', and the outer winding of the private magnet will be de-energized. Also, wiper 212 not finding ground potential on bank contact 208' the relay 255 will not be caused to actuate in a manner as hereinbefore described, and consequently the private magnet P2 de-actuates upon the wipers 212 90
20 to 215 rotating-off the bank contacts occupying bank position 21 so that the sideswitch wipers 210 and 219 are permitted to advance into their second position, whereupon relay 227 will actuate 95
25 and ground will be applied to wiper 213 and its engaged bank contact 209' in effecting the seizure of the line leading to telephone L22, in a manner as hereinbefore described. Had the bank contacts 208' and 209' constituted ground 100
30 potential due to the line leading to telephone L2 being busy, upon the wiper 212 engaging grounded bank contact 208' a circuit could be traced from said grounded contact, wiper 212, conductor 261, armature 260, conductor 253, spring 254, 105
35 armature 251, winding of relay 255, sideswitch wiper 210 to grounded battery, relay 255 actuating and opening the circuit to the rotary magnet R2. Due to wiper 213 finding ground potential on bank contact 209' the relay 263 is locked actuated, 110
40 which maintains the private magnet P2 actuated by reason of the grounded armature 272 being attracted. However, the attracted condition of armature 275 of relay 263 has no operative effect due to armature 221 being attracted. The 115
45 busy tone from source T2 is applied audible to the calling subscriber by way of armature 259 as hereinbefore described, indicative of the condition.

The operation of the connector A when co-operated with a local selector as SS in extending a call controlled by a local subscriber has been clearly set forth. The operation of the connector A wherein it is co-operated with a toll selector as B will now be detailed under various 120
50 assumed operative conditions.

Assume a call from cord-pair C to local telephone L12, the telephone number of which has been stated is "112". The seizure of selector B will be effected by the toll operator through the 125
60 agency of cord-pair C in the manner as hereinbefore described upon the sending of the first digit "1". Upon the second digit "1" being sent selector B will function in the manner as hereinbefore described wherein it raised its wipers 416 to 419, 479 and 483 into alignment with the second 130
65 bank level, responsive to the sending of digit "2", however, in the present instance, raising them into alignment with the first bank level in correspondence with the digit "1", where it will automatically rotate-in its wipers and seize the first 135
70 disengaged connector, which will be assumed is connector A, connected to bank contacts 489 to 494 over conductors 495 to 499 and 401'.

The general operation of selector B co-operating with connector A will be as described wherein

it co-operated with connector F. The functioning of connector A will be detailed while the functioning of the co-operating selector B will be referred to generally.

Upon the seizure of connector A by selector B 80
a circuit can be traced from upper winding of relay 201, spring 202, conductor 495, bank contact 489, wiper 416, conductor 454, armature 453 to grounded armature 412, relay 201 actuating, followed by the actuation of its dependent relay 204. 85
Grounded armature 206 will cause conductor 121 to constitute ground potential as hereinbefore described. A circuit can now be traced from grounded conductor 121, winding of converting relay 221', conductor 497, bank contact 491, wiper 418, armature 447, conductor 450, armature 451, resistance 456 to grounded battery, relay 221' actuating. Upon the calling toll operator sending the third digit "1", relay 402 will de-actuate and re-actuate one time responsive thereto, 90
wherein the traced circuit including the upper winding of relay 201 will be opened for an interval and the relay 201 will de-actuate and re-actuate one time responsive thereto and cause the vertical magnet V2 to raise the shaft carrying wipers 100
212 to 215 one step into alignment with the first bank level, the sideswitch wipers 210 and 219 advancing into their second position, in a manner as hereinbefore set forth wherein relay 201 was caused to operate under control of the calling 105
subscriber at telephone L, having in mind that the upper winding only of relay 201 is operatively energizing it. Upon the fourth and last digit "2" being sent, relay 402 will correspondingly operate, and also its dependent relay 201, whereupon the rotary magnet R2 will cause the wipers 212 to 215 to be rotated into engagement with bank contacts 222 to 225 respectively, in the manner as hereinbefore described with relation to the subscriber at telephone L calling telephone 115
110 L12.

Assume that the line leading to telephone L12 is idle and, therefore, bank contacts 222 and 223 do not constitute ground potential upon armature 260 retracting, the armature of private magnet 120
P2 will retract, and the same circuit-path as hereinbefore described, when wipers 212 to 215 engaged bank contacts 222 to 225 respectively, controlled by the subscriber at telephone L, will be energized causing relay 227 to actuate, and 125
ground potential to be applied to bank contact 223. Due to relay 221' being in its operated position, the hereinbefore traced path from the interrupted ringing current source G2 will not be established. However, upon the toll operator 130
applying ringing current through the agency of key e causing relays 466 and 471 to responsive actuate as hereinbefore set forth, the energizing circuit of relay 221' will be opened causing it to de-actuate, and a circuit will be closed from the 135
winding of relay 222', conductor 498, bank contact 492, wiper 419, armature 472, to its co-operating grounded contact, relay 222' actuating. A circuit can now be traced from grounded toll ringing generator GT2, conductor 223', armature 229, armature 230, armature 231, conductor 232, armature 233, wiper 215, bank contact 225, conductor 234, signal bell 305 of telephone L12, condenser 306, conductor 307, bank contact 224, wiper 214, armature 235, armature 237, armature 238, armature 239, resistance 224' to grounded battery, the signal bell 305 operating at the will of a calling toll operator. Upon the calling toll operator restoring ringing key e, relays 466, 471 and 140
145 150

- 222' will de-actuate in sequence, and relay 221' will re-actuate. function, depending upon armature 232' on relay 221' is effective only when the connector A is co-operated with a toll selector B.
- Upon the called subscriber at telephone L12 removing the receiver a circuit can be traced from the upper winding of relay 475, armature 476, winding 477, conductor 478, wiper 479, bank contact 493, conductor 499, armature 238, armature 237, armature 235, wiper 214, bank contact 224, conductor 307, receiver of telephone L12, conductor 234, bank contact 225, wiper 215, armature 233, armature 231, armature 230, conductor 401', bank contact 494, wiper 483, conductor 484, winding 485, armature 486 to lower winding of relay 475, relay 475 actuating. In view of windings 477 and 485 being in inductive relation to companion windings 409 and 408 respectively, the calling toll operator having key *g* manipulated the said operator is in telephonic relation with the called subscriber at telephone L12.
- Consequent to relay 475 actuating, the winding of relay 402 is disassociated and the winding of relay 403 is substituted therefor at armature 401, causing relay 508 to de-actuate and lamp 570 to extinguish as hereinbefore described.
- The release of selectors E and B is effected by the withdrawal of plug 501 as hereinbefore described, and due to the energizing circuit including the upper winding of relay 201 at armature 453 being opened thereby, relays 201 and 204 will deactivate in sequence and close a path from the winding of release magnet Re2, causing the shaft of connector A to be restored to normal in the manner as hereinbefore described, the circuits and equipment being now at normal.
- Assume that the line L12 is busy when wipers 212 and 213 engage tied bank contacts 222 and 223 respectively, the private magnet P2 will be maintained by way of spring 281, sideswitch wiper 219, conductor 226, wiper 213, to grounded contact 223, and a circuit can be traced from grounded contact 222, wiper 212, conductor 261, armature 260, spring 254, armature 251, winding of relay 255, wiper 210 to grounded battery, relay 255 actuating and applying a tone indicative of the condition audible to the calling toll operator, from tone source T2, armature 259, conductor 230', resistance 231', conductor 401', bank contact 494, wiper 483, conductor 484, winding 485, armature 486, to the lower winding of relay 475, causing an induced tone to be audible to the calling toll operator in a manner as hereinbefore described. A locking circuit is established for the winding of relay 255 from spring 254, armature 256, armature 257, spring 258, armature 232', conductor 226, wiper 213, to grounded bank contact 223, the locking circuit being thus dependent upon the 'busy' condition enduring on the line leading to telephone L12. Armature 256 also applies ground to contact spring 202' and to the inner winding of the private magnet P2, maintaining the private magnet and, therefore, restraining the sideswitch wipers 210 and 219 from advancing into their third position. However, since armature 256 is maintained grounded dependent upon the 'busy' condition of the line leading to telephone L12, the private magnet P2 will be maintained likewise dependent, so if the line leading to telephone L12 becomes idle and bank contact 223 therefore becomes ungrounded, the sideswitch wipers 210 and 219 will be permitted to advance into their third position and relay 255 will de-actuate because of its locking circuit becoming open. Under this condition, that of the busy line becoming idle, the tone will be disassociated and the connector will seize. This
- function, depending upon armature 232' on relay 221' is effective only when the connector A is co-operated with a toll selector B.
- Assume a call from cord-pair C to the premises of the subscriber whose telephone number is "1113" and who has a group of four lines (occupying bank positions 13 to 16) hereinbefore referred to. The operation on the part of the calling toll operator and the functioning of the various switches interlinking the connection will be the same as hereinbefore described with reference to the call to telephone L12, excepting, however, that the last digit in the present instance is "3" in lieu "2". The wipers 212 to 215 will, therefore, primarily attain engagement with bank contacts 282 to 285 respectively occupying bank position "13". At the time armature 260 retracts, and before armature 251 retracts, a circuit can be traced from grounded battery, winding 289 of tone source TT2, conductor 290, bank contact 282, wiper 212, conductor 261, armature 260, spring 254, armature 251, conductor 262, resistance 205' to lower winding of relay 263. However, due to the resistance 205' the relay 263 is not operatively energized. Upon the armature 251 retracting the circuit traced from battery through winding 289 to said armature, is applied through the winding of relay 255, wiper 210 to grounded battery, the path not being energized. Armature 275 not having attracted, the rotary magnet R2 is not energized to advance the wipers 212 to 215 from bank position 13 to bank position 14, regardless of any condition found on bank contact 283, as will appear.
- Assume that bank contact 283 does not constitute ground potential, there will be no energizing path completed including the outside winding of the private magnet, so the sideswitch wipers 210 and 219 will be permitted to advance into their third position, whereupon relay 227 will actuate and ground will be applied to bank contact 283 in the manner as hereinbefore set forth. A special tone as constituted in the special tone source TT2 can be traced from winding 289, conductor 290, bank contact 282, wiper 212, conductor 261, armature 260, conductor 253, armature 235', conductor 496, bank contact 490, wiper 417, armature 460, and over the described path including winding 409, operator's set N5, winding 408, armature 463, resistance 464 to ground. The said tone is thus audible to the calling toll operator, indicative that the called subscriber has a special toll loop, which may be manual or automatic as hereinbefore referred to. Due to bank contacts 284 and 293 and 285 and 286 being tied, respectively, the line leading to telephone L14 is seized at bank position 13, and the toll operator can cause the signal bell thereat to be operated in the manner set forth in relation to the telephone L12 and the connection can, therefore, be completed in a normal manner. However, since the tone received by the calling toll operator is indicative that the called subscriber has an independent toll loop the connector may be forthwith released in the manner as hereinbefore set forth and the call completed over the said toll loop.
- It will now be assumed that the wiper 213 encounters ground potential on bank contact 283, which is tied to bank contact 292, and that therefore, a circuit can be traced upon the retraction of relays 209 and 217 from grounded bank contact 282, wiper 213, conductor 226, wiper 219, armature 252, retardation coil *r*2, conductor 253, spring 254, armature 251, winding of relay 255, wiper 210 to battery, relay 255 actuating, apply-

ing tone audible to the calling toll operator in the manner as hereinbefore described. The tone hereinbefore described emanating from the source TT2, armature 235', will also ensue, but the tones 5 will be alternatively audible in the manner as hereinbefore referred to so that the calling toll operator will be apprised that the first line of the called subscriber's group is busy and also that he has an independent toll loop, or as has been referred to, that the tone emanating from tone source TT2 is indicative of some special fact concerning the called subscriber.

Assume now that upon the operator discerning the composite tone indicative of the two said conditions, that in lieu of completing the connection over the toll loop, which possibly is also busy, decides to complete the connection over one of the local lines of the group. In order to initiate the group selecting functioning of the connector 15 A, the calling operator will send digit "1", whereupon relay 201 will de-actuate and re-actuate one time, its grounded armature 205 applying ground to armature 208, armature 236', winding of slightly slow-releasing relay 237', armature 238' to 20 grounded battery on its working contact, relay 237' actuating. Armature 257 attracting unlocks relay 255, which prepares the rotary magnet circuit at armature 221 and disconnects the tone applied. A circuit can now be traced from grounded 25 spring 241, armature 240' to the upper winding of relay 263, relay 263 actuating and locks its upper winding through armature 252, wiper 219, conductor 226, wiper 213, to grounded bank contact 283. Thus, relay 263 will be locked actuated 30 as long as wiper 213 receives ground. The private magnet is maintained actuated by reason of ground received from armature 272, spring 281, to the outside winding thereof. A circuit can now be traced from armature 218, armature 273, armature 274, armature 275, armature 221, winding of the rotary magnet R2, wiper 210 to grounded battery. The rotary magnet R2 actuates and advances the wipers 212 to 215 into engagement with bank contacts 291 to 293, and 286 respectively. Upon the rotary magnet R2 attracting its armature 297 relay 296 will be caused to actuate in the manner as hereinbefore described, opening the energizing circuit of the rotary magnet, whereupon its armature will retract, followed by 40 the de-actuation of relay 296 in re-establishing the energizing circuit of the rotary magnet R2 provided the circuit has not been opened due to armature 275 retracting, upon wiper 213 failing to receive ground from bank contact 292, there- 45 by opening the locking circuit of relay 263. However, since bank contacts 283 and 292 are tied together, bank contact 292 will also constitute ground potential, so that the energizing circuit of the rotary magnet is re-established and the 50 wipers 212 to 215 are advanced into engagement with bank contacts 294 to 296 and 287.

If bank contact 295 does not constitute ground potential the locking circuit for relay 263 will be opened preventing the rotary magnet re-energizing 55 upon the retraction of armature 273, and the ground energizing the outer winding of private magnet P2 is also opened so that the private magnet de-actuates, permitting the wipers 210 and 219 to advance into their third position, where- 60 upon relay 227 will actuate and ground will be applied to bank contact 295 in the manner as hereinbefore described. The operator can now apply ringing current to the line leading to local telephone L15 in the manner as described in relation 70 to telephone L12.

It will now be assumed that bank contact 295 constitutes ground potential when engaged by wiper 213 and, therefore, the wipers 212 to 215 are advanced into engagement with bank contacts 298, 299, 201' and 288 respectively. Assuming further that bank contact 299 constitutes ground potential and, therefore, its tied bank contact 298 also constitutes ground potential. Upon the retraction of armature 260 and 251, a circuit can be traced from bank contact 298, wiper 212, conductor 261, armature 260, spring 254, armature 251, winding of relay 255, wiper 210 to grounded battery, relay 255 actuates and thereby incapacitates the rotary magnet R2 against further operation by reason of the attraction of armature 221. Relay 255 applies the busy tone audible to the toll operator in the manner as hereinbefore set forth. Ground from bank contact 299 is applied to wiper 213, conductor 226, wiper 219, armature 252, to the upper winding of relay 263 maintaining it locked so that armature 272 applies its ground to maintain the outer winding of the private magnet P2 energized to restrain the wipers 210 and 219 from advancing into their third position. It will be noted that relays 255 and 263 and 100 private magnet P2 are energized dependent upon the busy condition of the line L16 (corresponding to the bank position the wipers now occupy), terminating whereupon the sideswitch wipers 210 and 219 will advance into their third position and 105 the relay 227 will actuate forthwith to seize the line leading to telephone L16.

It will now be again assumed that when the connector A has its wipers in bank position 16 and that bank contacts 298 and 299 constitute 110 ground potential and that therefore, relays 255 and 263 and the private magnet P2 are locked energized as set forth, the calling operator desires to restore the shaft of connector A preparatory to re-testing the line of the group last 115 tested, or perhaps desires to effect a connection to some other line in the group. Possibly this line may be an exchange toll loop referring to the subscriber last called, or for other reasons. The calling operator will send digit "1", where- 120 upon relay 201 will de-actuate and re-actuate one time responsive thereto, and its grounded armature 205 will apply ground to armature 208, armature 236' winding of relay 237', armature 238' to grounded battery on its working contact, relay 237' actuating, unlocking relay 255. A circuit can now be traced from grounded bank contact 298, wiper 212, conductor 261, armature 260, conductor 253, armature 242', spring 265 to the winding of the release magnet Re2, the 131 release magnet actuating to restore the shaft to normal position, whereupon relay 263 and the private magnet P2 will be unlocked and the connector A will be in the condition as when primarily seized.

It will now be assumed that due to bank contacts 298 and 297 not constituting ground potential, the connector A seizes the line leading to telephone L16, it being the last line of the group, but that the calling toll operator for one 140 of the foregoing reasons, perhaps, desires to release the shaft of the connector A to normal position. The toll operator will send digit "1" whereupon relay 201 will de-actuate and re-actuate one time responsive thereto, and its armature 205 will apply its ground to armature 208, armature 236' winding of relay 237', armature 245' to grounded battery on its working contact. Under this condition, it will be borne in mind, that relays 255 and 263 are normal 145 150

and that the sideswitch wipers 210 and 219 are in third position and, therefore, bank contacts 298 and 299 constitute ground potential received through wiper 219. A circuit can now be traced 5 from grounded bank contact 298, wiper 212, conductor 261, armature 260, armature 242', spring 265, to the winding of the release magnet Re2, causing it to actuate and restore the shaft as hereinbefore set forth, whereupon the connector

10 A is in the condition as when primarily seized.

It will now be assumed that the telephone L15, occupying bank position 15, is wanted by the toll operator. This bank position is designated as telephone number "1115" and is perhaps 15 the only telephone of the group responsive at the hour called. The connection will be inter-linked in the manner as hereinbefore described, the last digit "5" causing the wipers 212 to 215 to be rotated into engagement with bank contacts 294, 295, 296 and 287 respectively. If bank contact 295 does not constitute ground potential the connector will seize in the manner as hereinbefore set forth, after which the calling toll operator can signal at will in the manner as 25 hereinbefore set forth and complete the connection.

It will now be assumed that the bank contact 295 constitutes ground potential by reason of the line leading to telephone L15 being busy.

30 In a previous description wherein the wipers of the connector A were directly caused to rotate from bank position 13 to bank position 15 under the control of the toll operator, and the encountered bank contact 295 was assumed to 35 constitute ground potential, the wipers were caused to automatically advance into bank position 16, under the condition of bank contact 295 constituting ground potential. Under that condition relay 263 was actuated. Under the 40 present condition relay 263 does not actuate, and therefore, an energizing circuit including the winding of the rotary magnet R2 will not be automatically closed. A circuit can now be traced from grounded bank contact 295, wiper 213, conductor 226, wiper 219, armature 252, retardation coil r2, conductor 253, spring 254, armature 251, winding of relay 255, wiper 210 to grounded battery, relay 255 actuating and applying a busy tone audible to the calling toll 45 operator in the manner as hereinbefore set forth. Due to ground being on wiper 219, derived from bank contact 295, the outside winding of the private magnet P2 will be energized by way of spring 281, thus restraining the wipers 210 to 50 219 from moving into their third position.

The toll operator can cause the connector A to restore its shaft to normal by sending digit "1" to first cause the connector to start functioning as a group-selecting connector. Resultant to armature 205 applying ground through armature 208, armature 236', winding of relay 237', armature 238' to grounded battery on its working contact, relay 237' actuates and relay 263 actuates and locks and relay 255 de-actuates. 60 This establishes the hereinbefore described energizing circuit for the rotary magnet wherein the connector is capacitated for group selection. When the wipers are rotated into bank position 16 which is also assumed busy, the shaft of the connector can be released by sending digit "1". If an idle line is found at bank position 65 16 the connector will seize in the manner as hereinbefore described, after which the toll operator can send the digit "1" and cause the

70 connector to restore its shaft to normal in the manner as has been described.

It will thus appear that the connector will release its shaft to normal resultant to digit "1" being sent only under the condition of the 75 wipers occupying the last bank position of a group and that the line corresponding to the last bank position is busy, or the connector has thereon seized a non-busy line.

In this connection it will appear that the tone source CT2 is normally applied through the lower off-normal spring to conductor 230', so that when the connector A has been seized by a toll selector B the calling toll operator perceives the tone which is indicative of the state. This tone will also be applied when the connector shaft is directly released, since the toll selector B is in seized relation with it. From this it will be clear that if the toll operator perceives a busy tone and then sends digit "1" and does not perceive the tone from source CT2 indicative that the connector shaft has restored to normal, it will be understood that the connector rotated in group-selection, and either seized an idle successive line of the group or, if a busy tone is 85 perceived, encountered the last line of the group and found it busy, whereupon digit "1" can be again sent to restore the connector shaft to normal position and apply the tone source CT2 audible to the calling toll operator. 90

It also follows that if there are a plurality of non-busy lines in the group successive to the bank position attained primarily, which was bank position 15, sending digit "1" will serve to advance the wipers only into seizure of the 95 first successive set of bank contacts found non-busy and, therefore, as many digits "1" will 100 have to be sent in order to release the connector as there are idle lines in the group successive to the one primarily called, remembering that the 105 idle or busy condition of the last line of the group will not alter the operation whereby the sending of digit "1" will release the shaft to normal. 110

The subscriber having telephone number "1113" has a dead bank position 13 so far as a 120 specific corresponding line is concerned. If it is desired to have an exchange toll loop terminate in bank position 13, conductors 829 and 830 will be disconnected from conductors 831 and 832 and attached to conductors 833 and 834 leading to telephone L13, respectively. The conductor tying conductors 813 and 814 will be removed. The conductor 814 may be run to the winding of a cut-off relay corresponding to relay 302, for 125 example. Bank contact 282 will be disassociated 130 from tone source TT2 and associated with tone source TL2 in lieu thereof, so that a calling toll operator will receive the tone indicative of the condition when the connector seizes the said toll loop. 135

It will now be assumed that the toll operator desires to call telephone L22, the telephone number of which is "1121". The connection will be inter-linked in the manner as hereinbefore described, the last digit "1" causing the wipers 212 to 215 to be driven into engagement with the bank contacts, occupying bank position 21. Wiper 212 engages bank contact 204' which constitutes high voltage battery potential received from battery B2. Upon armature 260 retracting, a circuit can be traced from battery B2, conductor 206', bank contact 204', wiper 212, conductor 261, armature 260, spring 254, armature 251, conductor 262, resistance 205' to the lower winding of relay 263. The voltage of battery B2 is 140 145 150

of such value that relay 263 will be operatively energized, notwithstanding the inclusion of resistance 205' and, therefore, upon the retraction of armature 218 a circuit can be traced from said 5 armature, armature 273, armature 274, armature 275, armature 221, winding of the rotary magnet, wiper 210 to grounded battery, the rotary magnet R2 operating to advance the wipers 212 to 215 to the next bank position 22, incidently energizing relay 296 and opening the energizing circuit at armature 273, causing the armature of the rotary magnet to retract preparatory to advancing the wipers an additional step to bank position 23 if the energizing circuit is not opened 10 at armature 275 or armature 221. Armature 275 will retract if wiper 213 fails to find ground in the manner as hereinbefore set forth, and armature 221 will attract provided relay 255 is caused to actuate, which latter condition can only occur, 15 if wiper 212 receives ground. In view of bank contacts 208' and 209' being tied, if bank contact 209' constitutes ground potential the relay 255 will be caused to actuate and incapacitate the rotary magnet R2 and apply busy tone audible to the toll operator in the manner as hereinbefore described. It will thus appear that upon 20 the wipers of connector A attaining bank position 21 the connector will forthwith function as a group-selecting connector when seized by a local or by a toll selector.

It will now be assumed that the calling toll operator desires to extend a connection from springjack L shown in Fig. 9 through answering plug 580 and connecting plug 501 through 25 springjack D to the premises of the subscriber having telephone "1123". The connection will be interlinked in the manner as hereinbefore described, the last digit "3" causing the wipers 212 to 215 to be rotated into engagement with bank contacts occupying bank position 23, wiper 212 engaging bank contact 266, which latter constitutes battery potential derived through winding 270 of tone source TL2. Assuming that bank contact 267 does not constitute ground potential 30 and, therefore, the connector A will seize in the manner as hereinbefore set forth and a tone from source TL2 will be applied audible to the calling toll operator by way of conductor 271, bank contact 266, wiper 212, and over the described path to armature 463, resistance 464, and to ground indicative that the called line seized is an exchange toll loop, whereupon the calling toll operator can proceed to signal telephone T23 at will in the manner as hereinbefore set forth 35 in relation to calling telephone L12 and get a response, causing the equipments to function as in the call last referred to.

It will now be assumed that bank contact 267 constitutes ground potential. The current derived through tone source TL2 not being sufficient to operatively energize relay 263 with the winding 205' included in circuit therewith the connector A will not function as a group selector in automatically rotating its wipers into bank 40 position 24. However, a circuit can now be traced from grounded bank contact 267, wiper 213, conductor 226, wiper 219, spring 281 to the outer winding of the private magnet P2 maintaining it energized to restrain the wipers 210 and 219 from 45 advancing into their third position. Also, ground received through wiper 219 will be applied through armature 252 retardation coil r2, conductor 253, spring 254, armature 251, winding of relay 255, wiper 210 to grounded battery, relay 50 255 actuating and applying a busy tone audible

to the calling toll operator, indicative of the condition. The superimposed tone on conductor 271 will be applied to bank contact 266, wiper 212, conductor 261, armature 260, conductor 253, armature 235', conductor 496, over the described path including armature 463, resistance 464 to ground, audible to the calling toll operator, indicative that the line engaged and found busy is an exchange toll loop, the said two tones being being alternatively applied in the manner as hereinbefore referred to. 50

Assume that the call is desired completed forthwith, that is, that the toll operator does not wish to hold the connection awaiting the disengagement of exchange toll loop leading to telephone T23, but on the other hand, desires a connection over the local line. The connector can be forthwith capacitated to function as a group selecting connector by sending digit "1", whereupon relay 201 will de-actuate and re-actuate one time responsive thereto, wherein armature 205 will apply its ground to armature 208, armature 236', winding of relay 237', armature 238', to grounded battery on its working contact, relay 237' actuating and applying ground 55 from spring 241 to the upper winding of relay 263 and unlocks relay 255, whereupon relay 263 will actuate and close the hereinbefore described energizing circuit for the rotary magnet, causing it to advance the wipers 212 to 215 into engagement with bank contact 276 to 279 respectively. At the time relay 263 actuated, armature 252 locked the upper winding through wiper 219, conductor 226, wiper 213, to grounded bank contact 267. If bank contact 277 constitutes ground 60 potential, the tied bank contact 276 will also constitute ground potential, whereupon a circuit can be traced from bank contact 276, wiper 212, conductor 261, armature 260, spring 254, armature 251, winding of relay 255, wiper 210 to grounded 65 battery, relay 255 actuating applies the tone, indicative of the condition in the manner as hereinbefore set forth, the rotary magnet being incapacitated against further operation. 70

If the toll operator desires to release the shaft 120 of connector A to normal position, digit "1" will be sent, causing relay 201 to de-actuate and re-actuate one time, armature 205 applying its ground through armature 208, armature 236', winding of relay 237', armature 238' to grounded 125 battery on its working contact, relay 236' actuating. A circuit can now be traced from grounded contact 276, wiper 212, conductor 261, armature 260, conductor 253, armature 242' spring 265 to the winding of release magnet Re2, causing 130 it to re-actuate to restore the shaft of connector A to normal position, whereupon the connector A will be in the condition as when primarily seized.

If, in the last assumed instance, the line 135 leading to telephone L24 was not busy, but that no response was obtained for example, the connector having seized, upon the calling toll operator sending digit "1", causing relay 201 to de-actuate and re-actuate one time, armature 205 140 will apply its ground through armature 208, armature 236', winding of relay 237', armature 245' to grounded battery on its working contact. A circuit can now be traced from ground, wiper 219, conductor 226, wiper 213, bank contact 277, 145 conductor 280, tie conductor 804, conductor 805, bank contact 276, wiper 212, conductor 261, armature 260, armature 242', spring 265 to the winding of the release magnet Re2, causing it to 150 actuate and restore the shaft of connector A to

normal position, whereupon the connector will be in the condition as when primarily seized.

It will be assumed that the subscriber at telephone T23 desires to obtain the response of the recording toll operator at the exchange toll switchboard H. Upon removing the receiver from the switchhook at telephone T23 a circuit can be traced from the winding of slow-releasing relay 320, armature 321, conductor 322, receiver of telephone T23, conductor 324, armature 325, to its resting ground contact, relay 320 actuating.

A circuit can be traced from grounded armature 326, conductor 327, winding of relay 304, conductor 328, armature 329 to the winding of motor magnet M3, relay 304 actuating.

If bank contact 330 constitutes ground potential at the time relay 320 actuates, a circuit can be traced from said grounded contact 330, wiper 331, armature 332, armature 333, conductor 328, armature 329, to the winding of motor magnet M3, operatively energizing it. Under this condition it will be noted that the winding of relay 304 has ground potential on both of its terminals and, therefore, will not be energized. Upon motor magnet M3 attracting its armature 329 it opens its energizing circuit and it will retract, driving the wipers 334, 335, 331 and 336 a rotary step, and if the wiper 331 fails to encounter a grounded bank contact, ground potential will be removed from conductor 328, and relay 304 will be operatively energized in series with the winding of motor magnet M3. However, the motor magnet M3 will not operatively energize with the winding of relay 304 included therewith.

Going back to the condition wherein bank contact 330 did not constitute ground potential, and wherein relay 304 actuated resultant to the attraction of armature 326. A circuit can be traced from the upper winding of relay 340, conductor 341, bank contact 342, wiper 334, armature 321, conductor 322, receiver of telephone T23, conductor 324, armature 325, wiper 335, bank contact 345, conductor 346, to the lower winding of relay 340, relay 340 actuating. A circuit can be traced from the winding of slow-releasing relay 347, armature 348, to its working grounded contact, relay 347 actuating. Ground from working contact 350 is applied through conductor 351, bank contact 330, wiper 331, armature 332 to conductor 327, before relay 320 de-actuates and opens the ground from conductor 327 at its armature 326. Relay 304 is thus maintained over conductor 351, dependent upon relay 340. A circuit can be traced from the upper winding of relay 701, upper winding of relay 702, armature 703, conductor 705, winding of retardation coil 352, armature 355, conductor 357, armature 708, lower winding of relay 702 to the lower winding of relay 701, relay 702 actuating, relay 701 remaining normal, due to the windings thereof energizing its core differentially. A circuit can be traced from the winding of slow-releasing relay 709 to grounded armature 711, relay 709 actuating. Grounded contact 712 is applied to armature 713 and to conductor 714 and to armatures 715 and 716.

Relay 320, due to its slow-releasing characteristic maintains its armature 360 attracted for a brief period after relay 304 actuates, causing relay 340 to actuate, followed by relay 702 and 709 actuating. After the stated relays have actuated, with armature 360 still attracted, a circuit can be traced from grounded armature 361, armature 360, wiper 336, bank contact 361, conductor

362, conductor 705, armature 703, upper winding of relay 702, to upper winding of relay 701. Thus, the return current normally returning through retardation coil 352, armature 355, conductor 357, armature 708, lower winding of relay 702 to the lower winding of relay 701, is short-circuited and, therefore, the lower winding of relay 701 will not neutralize the tractive effort of the upper winding thereof, so relay 701 will actuate co-incident with the actuation of relay 702, the traced return path including the lower windings of relay 702 and 701, not being energized until armature 360 retracts. While armature 360 is attracted, a circuit can be traced from grounded armature 720, armature 721, spring 722, spring 723 of rotary off-normal set RON (which is designed to operate upon the first rotary off-normal movement of the shaft of selector I carrying wipers 724 to 726), to the winding of shunted interrupter relay 727, relay 727 actuating. A circuit can now be traced from grounded armature 713, armature 715, armature 716 to the winding of rotary magnet R7, the rotary magnet R7 actuating to advance the wipers 724 to 726 into engagement with bank contacts 731 to 733 respectively. Incidental to the first off-normal movement of the shaft, spring 723 will engage spring 735. Therefore, if bank contact 731 should constitute ground potential due to the equipment H being busy, in a manner as will appear, a circuit can be traced from grounded contact 731, wiper 724, armature 736, conductor 737, armature 738 on the rotary magnet R7, spring 735, spring 723, to the winding of relay 727, causing it to actuate and close a locking circuit from grounded contact 740, armature 738, spring 735, spring 723 to the winding of relay 727. At the same time a circuit will be established from the winding of rotary magnet R7, armature 716, armature 715 to grounded armature 713, the rotary magnet advancing the wipers into engagement with bank contacts 741 to 743 respectively. Due to armature 738 attracting, the described locking circuit for relay 727 is opened and it will de-actuate, whereupon if the equipment corresponding to H leading from the said latter bank contacts is busy, wherein bank contact 741 will constitute ground potential, the described cycle of operations with respect to relay 727 and rotary magnet R7 will re-ensue, continuing as long as wiper 724 receives ground potential from an engaged bank contact.

Assuming that bank contact 731 does not constitute ground potential when first engaged by wiper 724, upon the de-actuation of relay 727, ground potential will not exist on the lower winding terminal of relay 745 and a circuit can be traced from the winding of relay 727, spring 723, spring 735, armature 738, conductor 737, winding of relay 745, conductor 714 to grounded armature 713, relay 745 actuating to effect the seizure of the selector. Relay 727 is adjusted marginally so that it will not actuate when its winding is included in series with the winding of relay 745, but relay 745 will actuate under the stated condition. A circuit can be traced from the upper winding of relay 746, conductor 748, bank contact 732, wiper 725, armature 703, conductor 705, winding of retardation coil 352, armature 355, conductor 357, armature 708, wiper 726, bank contact 733, conductor 749, to the lower winding of relay 746, relay 746 actuating. A circuit can now be traced from grounded contact 751, armature 752, lamp 753, to grounded battery, lamp 753 glowing as a calling signal to the toll recording operator at the exchange toll switch-board. A

circuit can be traced from grounded armature 754, conductor 755, to bank contact 731; this occurring before relay 709 de-actuates, consequent to the disassociation of the windings of relay 702 at armatures 703 and 708, so that ground is maintained on conductor 714 after the de-actuation of relay 709, by way of armature 736 and, therefore, the selector I is maintained dependent on ground being maintained on conductor 755 from the equipment H.

It will thus be clear that upon the calling subscriber at telephone T23 removing the receiver from the switchhook the lineswitch LS3' will automatically function to attain connection with the first seizable trunk between the main-branch office to which the line leading from telephone T23 leads, to the main-branch office from which the equipment H is seizable to a first selector, which in this case is an incoming first selector terminating an inter-office trunk. Further, that the second selector terminating the inter-office trunk will, upon seizure by the lineswitch LS3', initiate its operation as a selector rotating on its normal level, without having first stepped vertically off-normal, and seize a trunk leading to the equipment H. The lamp 753 is thus caused to glow upon the subscriber at telephone T23 removing the receiver from the switchhook, simply.

The operator upon observing lamp 753 glowing will insert switching plug t of cord-pair G into the springjack n and manipulate listing key m. A circuit can now be traced from ground, sleeve conductor 756, thimble 757, winding of relay 758, relay 758 actuating, whereupon lamp 753 will extinguish.

The calling subscriber at telephone T23 is now in telephonic communication with the responding toll operator through telephone set N7, traced from telephone T23, conductor 324, armature 325, wiper 335, bank contact 345, conductor 346, condenser 365, conductor 357, armature 708, wiper 726, bank contact 733, conductor 749, spring 759, conductor 760, spring 761, receiver and secondary winding of the operator's induction coil spring 762, conductor 763, spring 764, conductor 748, bank contact 732, wiper 725, armature 703, conductor 705, condenser 366, conductor 341, bank contact 342, wiper 334, armature 321, conductor 322 to the telephone T23.

Relays 746 and 758 are mechanically inter-linked, the armature 767 controlling armature 765 and the armature 765 controlling armature 767. That is to say, if relay 746 actuates, due to a call being initiated, the armature 765 is limited so it cannot make its co-operating contact. However, if relay 746 is normal, or retracts while relay 758 is actuated, as shown in Fig. 7A, due to a plug t being in springjack 757, for example, the armature 767 is limited so it cannot disengage its resting contact. Thus, it will be clear that if the toll operator responds to the glowing of lamp 753 the circuit of lamp 766 is open at both its terminal contacts. However, if the calling party replaces the receiver at telephone T23 and causes relay 746 to de-actuate as set forth hereinbefore, the armature 767 will retract against its resting contact and the armature 765 will attract against its working contact, causing the lamp 766 to glow as a clearing signal.

It will be noted that due to armature 765 being attracted and close to the core of the relay when plug t is in springjack n, in case a selector as I seizes the equipment H after it becomes unguarded by reason of relay 746 de-actuating the armature 767 is limited so it cannot attract from

its resting contact and thereby open the energizing circuit for the lamp 766. Armatures 754 and 752 will attract against their working contacts and apply ground to conductor 755 and lamp 753 will receive ground from armature 765.

80

The operator observing the lamp 766 glowing will know the calling party has released. Then, when the plug t is withdrawn from springjack n the armature 767 will be unblocked so it can attract and extinguish the lamp 766, and the lower armature of relay 758 retracting against contact 751, allows the circuit of calling lamp 753 to be alternatively established to cause the lamp 753 to continue to glow as a calling signal for a new call. Therefore, if the calling party replaces the receiver and a new calling party gains connection with the then unguarded equipment H before the operator has observed the clearing signal, the calling signal will be re-energized though the plug is not withdrawn responsive to the clearing signal. Contact 790 is made when armature 765 is fully attracted, only.

150

It is thus manifest that the novel interlinking of relays 746 and 758 affords a clearing signal to indicate that the calling party has released from the initiated connection, and also indicates if a newly established connection has been substituted for the released one.

Were this provision not made, wherein lamp 753 is prevented from re-glowing, a new call might be made immediately after a former call had been released by the calling subscriber and the toll operator would possibly not have due notice of the fact that the first subscriber had terminated the connection and had been replaced by a new calling subscriber.

Upon the calling subscriber at telephone T23 replacing the receiver on the switchhook, causing relay 340 to de-actuate and open the energizing circuit for relay 746 wherein ground from armature 754 is removed from conductor 755, relay 745 will deactuate. A circuit can now be traced from the winding of the release magnet Re7, spring 769, armature 770, armature 771, to grounded armature 711, the release magnet operating to restore the selector I to normal position. Consequent to the retraction of armature 348, relay 347 will deactuate, and remove the ground from lower winding of relay 304 causing it to de-actuate.

Having in mind that the trunk leading from repeater R3 and terminating in selector I is an inter-office trunk used for general subscriber switching in addition to the auxiliary use described in relation to the call to the exchange toll switchboard, a call will be assumed from local telephone E3, belonging to the same main-branch office as telephone T23, to telephone L7 located in the main-branch office from which the trunks to equipment H lead the telephone number of which is "3211". Upon the subscriber at telephone E3 removing the receiver from the switchhook, the lineswitch LS3 will function in the manner as hereinbefore referred to and attain the seizure of first selector FS3. Upon the calling subscriber at telephone E3 manipulating the calling device 370 thereat in accordance with the first digit "3" the shaft of selector FS3 will be caused to be raised three vertical steps into alignment with the third bank level thereof, and there automatically rotate-in and seize the first idle bank contact set 371 to 373 leading to repeater R3 in common relation with bank contacts 330, 342 and 345, respectively, of the lineswitch LS3'. A circuit can now be traced from the upper winding of relay 340, bank contact 372, 150

- wiper 374, conductor 375, wiper 376, conductor 377, receiver of telephone E3, conductor 378, wiper 379, conductor 380, wiper 381, bank contact 373, to the lower winding of relay 340, relay 340 actuating and closing the described energizing circuit for relay 702, in selector I, whereupon relay 709 will actuate as before described. Due to the differential windings on relay 701 it will not actuate because conductor 362 has not applied ground potential to conductor 705 to unbalance it and, therefore, the selector I does not initiate the movement of its shaft in rotating its wipers as hereinbefore described wherein relay 701 was caused to actuate.
- Upon the calling subscriber sending the second digit "2" relay 340 will de-actuate and re-actuate two times responsive thereto, and cause relay 702 to correspondingly operate. Upon each retraction of armature 711 its ground will be applied through armature 771, armature 770, series winding of slow-releasing relay 772 to the winding of the vertical magnet V7, causing the relay 772 to attract its armature 715 and sustain it over the lapse between the two impulses and operate the vertical magnet to raise the shaft carrying wipers 724 to 726 two vertical steps, the said wipers aligning with the second bank level. Off-normal set ON7 is operated incidental to the first off-normal movement of the shaft and, therefore, when the shaft steps off-normal a circuit can be traced from grounded armature 713, armature 715, spring 773, to the winding of relay 727, causing it to actuate and lock by way of armature 738 and grounded contact 740. Upon the retraction of armature 715 its period following the second impulse applied to the vertical magnet V7 a circuit can be traced from grounded armature 713, armature 715, armature 716 to the winding of rotary magnet R7, causing it to actuate and drive the wipers 724 to 726 into engagement with bank contacts 774 to 776 respectively. At the same time, armature 738 will open the traced locking circuit of relay 727, whereupon it will de-actuate. If bank contact 724 constitutes ground potential due to the wiper corresponding to 724 thereof of some other selector being connected with it, upon the retraction of armature 738 a circuit can be traced from grounded bank contact 774, wiper 724, armature 736, conductor 737, armature 738, spring 773, to the winding of relay 727, causing it to actuate and establish its locking circuit as previously traced, wherein the rotary magnet R7 will again operate to advance the wipers an additional rotary step, the cycle continuing as long as wiper 724 encounters ground.
- Assuming that bank contact 724 does not constitute ground potential and, therefore, the lower winding terminal of relay 745 will not constitute ground potential, a circuit can be traced from the winding of relay 727, spring 773, armature 738, conductor 737, winding of relay 745 conductor 714, to grounded armature 713, relay 745 actuating and relay 727 remaining normal due to its marginal characteristic. The bank contacts 774 to 776 are now seized, and a circuit can be traced from the line relay in connector CS7 corresponding to relay 601 in connector F, whereupon a relay in connector CS7 corresponding to relay 606 will operate to apply ground potential to conductor 777 before relay 709 de-actuates due to the attraction of armatures 703 and 708 incidental to the seizure of selector CS7 by selector I.
- Upon the calling subscriber sending the last two digits "11" the connector CS7 will function in the manner as hereinbefore described with relation to connector F wherein it seized the line leading to telephone L6, the wipers 778 to 780 attaining connection with the bank terminals 781 to 783, corresponding to the line leading to local telephone L7, and automatically apply ringing current operative to the signal bell 784 of telephone L7.
- Upon the called subscriber at telephone L7 removing the receiver from the switchhook, a telephonic circuit will exist from calling telephone E3 to bank contact 372 and 373 as traced and from bank contact 372, condenser 366, conductor 705, armature 703, wiper 725, bank contact 775, conductor 785, wiper 779, bank contact 782, conductor 786, receiver of telephone L7, conductor 787, bank contact 783, wiper 780, conductor 788, bank contact 776, wiper 726, armature 708, conductor 357, condenser 365 to bank contact 373.
- The release of selector FS3 and its co-operating line-switch LS3 is dependent upon relay 340 de-actuating upon the receiver of telephone E3 being replaced on the switchhook. The relay in connector CS7 corresponding to relay 601 in connector F being energized dependent upon armature 355 in the repeater R3, will de-actuate and ground will be removed from conductor 777, whereupon relay 745 will de-actuate and a circuit may be traced from the winding of release magnet Re7, spring 790, spring 791, armature 770, armature 771 to grounded armature 711, the release magnet operating to restore the shaft of selector I to normal.
- In this connection it will be noted that spring 769 and its co-operating spring are tied to springs 791 and 790 respectively. In the last traced circuit the two sets of springs last mentioned are closed respectively, therefore, the operation of spring 769 is to no operative purpose. However, since the rotary off-normal set RON does not operate until a rotary off-normal movement, in case it were desired to release the selector I before it rotated-in it could not be accomplished due to there being no traceable circuit including the winding of the release magnet, were the said tied springs not so tied. It will be further noted in this connection that springs 792 and 793 apply ground and battery to the lower and upper winding terminals of relay 701 upon the first off-normal movement of the shaft and, therefore, short-circuit the winding of relay 701 under this condition, since the relay 701 has no operative function after the shaft steps off-normal vertically.
- In commercial systems the toll loop subscribers having a telephone such as is telephone T23, may be classified to suit the convenience of the operating concern. For example, certain of the subscribers may have peculiar conditions such as requiring certain individuals to authorize the outgoing toll service, wherein it will be necessary to have some means of prompting the responding toll operator to consult records with relation to the call or not. Under this condition the toll loop subscribers of the various classes would have access to certain groups of inter-office trunks terminating in selectors such as I. The selectors such as I would be classified and have access to certain groups of equipments H specific to them, so that a call originated from any particular class of toll loop subscribers will be directed into a particular class of inter-office trunks terminating in a particular class of selectors as I, and these in turn, will have access to a particular class of toll recording position trunks as H, so depending

upon what lamps, such as 753, glow the responding toll operator will be apprised as to the class of toll loop subscriber calling.

It was stated at the outset that the exchange system chosen to elucidate the present invention was a four-digit system. That is to say, the system would have ten groups of one thousand subscribers as an ultimate or nominal capacity. It is to be understood that these groups could be placed into ten corresponding main-branch offices, each containing one thousand subscriber capacity, there being inter-office trunks for effecting connection between subscribers of different one-thousand groups. For example, the telephone L7 will be in the "3" thousand group. The telephones L12 and L24 belong to the "1" thousand group and the telephone L6 and L6' belong to the "2" thousand group. It may be assumed that the "1" thousand group and the "2" group are located contiguously in the same main-branch office while the "3" thousand group is located in a remote main-branch office and, therefore, requires a special repeater R3 which will localize the battery for exciting the telephone in the "1" main-branch office, when a connection is directed to a telephone in the "3" main-branch-office.

Repeaters for localizing the battery supply for trunk connections is not new. However, the arrangement contemplated under the present invention wherein lineswitches have access to these trunks as well as selector switches, and wherein the terminating selector is designed to function automatically upon the seizure of the trunk by a lineswitch and not to function automatically when seized by a selector is novel, as well as other features relating thereto as have been described are believed to be novel.

In view of the foregoing description it is manifest that a system involving five-digit telephone numbers, or a greater plurality of digits, can be readily organized without departing from the scope of the present invention in view of the subjoined claims, by introducing a third selector (or a plurality of successively operating selectors) intermediate of the second selector SS (similar to SS) and a connector as F with which selector SS has been described as co-operating. In the same manner a selector similar to E can be introduced intermediate of the selector E and the selector B with which it has been described as co-operating directly. Also, a selector similar to FS3 or I can be introduced intermediate of selector I and connector CS7. Of course, the introduction of a selector (or selectors) in the manner referred to will imply that an additional digit (or digits) will have to be sent corresponding thereto in inter-linking a connection such as has been described.

It is thus manifest that the present invention can be applied to commercial telephone systems either as an amplification of the exampled system described for its illustration, or as a curtailment thereof wherein but a portion of the devices of the present invention is employed, or wherein the combinations and details of the elements are modified and altered, without departing from the scope of the subjoined claims.

I claim:

1. In a telephone system, a calling line, a called line, a tone source permanently associated with the called line indicative of a specific state thereof, a connector, means for directly operating the connector to connect the calling with the called line, and automatic means for applying the tone source audible along the calling line.

2. In a telephone system, a calling line, a called line, a tone source permanently associated with the called line indicative of a specific state thereof, a connector, means for directly operating the connector to connect the calling with the called line, means for applying the tone source audible along the calling line, and automatic means for disconnecting the applied tone consequent to a response being obtained on the called line.

3. In a connector for completing a connection from a calling line to a called line of a group, a means controlled from the calling line for initiating a group selective operation of the connector after the connector has selected a line of the group whereby the connection is at will selectively progressed to a successive line of the group.

4. In a connector for completing a connection from a calling to a called line and which will function as an automatic hunting selector, means directly controlled from the calling line for at will initiating a continued hunting operation of the connector after it has effected a connection with the called line.

5. In a connector for completing a connection from a calling to a called line and which will function as a hunting selector, means directly controlled from the calling line for setting the connector in selected relation to a called line regardless of its idle or busy state, and means thereupon directly controlled from the calling line for forthwith initiating the hunting selective operation of the connector whereby it will be progressed from the first set position.

6. In a connector for completing a connection from a calling to a called line and which will function as a hunting selector, means directly controlled from the calling line for setting the connector in selected relation with a called line regardless of its idle or busy state, and means thereupon directly controlled from the calling line for forthwith initiating the hunting selective operation of the connector whereby it will be progressed from the first set position and seize the first idle line encountered.

7. In a group-selecting connector for completing a connection from a calling line to an idle line of a group, means directly controlled from the calling line for setting the connector in selected relation with a called line of the group regardless of its busy or idle state, and means thereupon directly controlled from the calling line for forthwith initiating the automatic group-selecting operation of the connector whereby it will be automatically progressed from the first set position.

8. In a telephone system, a calling line and a first called line, a second called line, a group-selecting connector for completing a connection from the calling line, means for directly controlling the connector whereby the calling line is extended to the said first called line, and means for thereupon at will directly controlling the connector for forthwith automatically selectively progressing the connection by a group-selecting operation from the first called line to the second called line whereby the calling line will be changed from its connection with said first called line to a connection with said second called line.

9. In a telephone system, a calling line and a first called line of a group, a second called line of the group, a group-selecting connector for completing a connection from the calling

- means for directively controlling the connector for setting it in selected relation with the said first called line regardless of its busy or idle state, and means thereupon directively controlled 5 from the calling line for forthwith initiating the group-selecting operation of the connector whereby it will be progressed from the first set position to the position occupied by the said second called line.
10. In a telephone system, a calling line, a connector, a group of successively disposed lines any of which may be connected with directively through said connector, said connector being a group-selecting connector and a non-group-selecting connector, means whereby said connector may automatically advance as a group-selecting connector if the first line of the group is initially selected but not automatically advanced as a group-selecting connector if a successive line 20 of the group is initially selected.
11. In a telephone system, a calling line, a connector, a group of successively disposed lines any of which may be called step-by-step directively through said connector, said connector being a group-selecting connector and a non-group-selecting connector, means whereby said connector may automatically advance as a group-selecting connector if the first line of the group is initially selected but not automatically advanced as a group-selecting connector if a successive line 30 of the group is initially selected, means for directively operating the connector for setting it in selected relation to the first line of the group, and automatic means for thereupon initiating the automatic group-selecting functioning of the connector for selectively testing other lines of the group and for seizing the first tested idle line thereof.
12. In a telephone system, a calling line, a connector, a group of successively disposed lines any of which may be called step-by-step directively through said connector, any line of the group excepting the first line thereof being seizable by the connector, said connector alternatively operable as a group-selecting connector and a non-group-selecting connector, means for directively operating the connector for setting it in selected relation to the first line of the group, and automatic means for thereupon initiating the automatic group-selecting functioning of the connector for selectively testing other lines of the group and for seizing the first tested idle line thereof.
13. In a telephone system, a calling line, a connector, a group of successively disposed lines any of which may be called directively through said connector, any line of the group excepting the first line thereof being seizable by the connector, said connector alternatively operable as a group-selecting connector and as a non-group-selecting connector, means for directively operating the connector for setting it in selected relation to the first line of the group, means for directively operating the connector for setting it in selected relation to any following line of the group, automatic means for initiating the automatic group-selecting functioning of the connector for selectively testing other lines of the group and for seizing the first tested idle line thereof if the first line of the group is called, and means for seizing a specifically directively called line of the group as a non-group-selecting connector if idle and not seizing it if busy if the said specifically called line is a line of the group other than the first line thereof.
14. In a telephone system, a calling line, a connector, a group of successively disposed lines any of which may be called directively through said connector, any line of the group excepting the first line thereof being seizable by the connector, said connector alternatively operable as a group-selecting connector and as a non-group-selecting connector, means for directively operating the connector for setting it in selected relation to the first line of the group, means for directively operating the connector as a non-group-selecting connector for setting it in selected relation to any following line of the group, automatic means for initiating the automatic functioning of the connector as a group-selecting connector for selectively testing other lines of the group and for seizing the first tested idle line thereof if the first line of the group is called, means for seizing a specifically directively called line of the group as a non-group-selecting connector if idle and not seizing it if busy if the said specifically called line is a line of the group other than the first line thereof, and means for at will directively unseizing the seized line and for initiating the group-selecting operation of the connector for hunting and seizing the first successive idle line of the group if the said specifically called line is seized by the operating connector.
15. In a telephone system, a calling line, a connector, a group of successively disposed lines any of which may be called directively through said connector, any line of the group excepting the first line thereof being seizable by the connector, said connector alternatively operable as a group-selecting connector and as a non-group-selecting connector, means for directively operating the connector for setting it in selected relation to the first line of the group, means for directively operating the connector as a non-group-selecting connector for setting it in selected relation to any following line of the group, automatic means for initiating the automatic functioning of the connector as a group-selecting connector for selectively testing other lines of the group and for seizing the first tested idle line thereof if the first line of the group is called, means for seizing a specifically directively called line of the group as a non-group-selecting connector if idle and not seizing it if busy if the said specifically called line is a line of the group other than the first line thereof, and means for at will directively unseizing the seized line and for initiating the group-selecting operation of the connector for hunting and seizing the first successive idle line of the group if the said specifically called line is seized by the operating connector.
16. In a telephone system, two alternative selectors for cooperation with a connector for extending a connection from a calling line to a called line, called lines of two classes in the same level group, and means whereby lines in one of said classes are thereby barred against seizure by the connector when the connector is cooperated with one of the said selectors and is not barred when it is cooperated by the other selector.
17. In a telephone system, two groups of alternative selectors for cooperation with a connector for extending a connection from two classes of calling lines respectively to a common level group of called lines, and means whereby a line of the said called group is barred against seizure by the connector when the connector is cooperated with a selector of one group and is not barred against seizure by the connector.

when the connector is cooperated with a selector of the other group.

18. In a telephone system, two groups of alternative selectors for cooperation with a connector for extending a connection from two classes of calling lines respectively to a common group of called lines, means whereby a line of the said called group is barred against seizure by the connector when the connector is cooperated with a selector of one group and is not barred against seizure by the connector when the connector is cooperated with a selector of the other group, and automatic means made operative responsive to the connector encountering the barred line for causing the connector to selectively progress in a hunting operation from the barred line and selectively test and seize the first tested idle line of the group.

19. In a telephone system, two groups of selectors for alternative cooperation with a connector through specific terminal sets for extending connection from two classes of calling lines respectively to a common level group of called lines, and means whereby a line of the said called group is barred against seizure by the connector when the connector is cooperated with a selector of one group and is not barred against seizure by the connector when the connector is cooperated with a selector of the other group.

20. In a telephone system, a first switch for connection to a trunk line, said trunk line terminating in a second switch directly controlled through the first switch over the trunk for extending a connection from the said first switch in the direction of a first called line, a third switch terminating a calling line also having access to the said trunk, a second called line, and means whereby initiating a call on the calling line by a single manual operation will thereby automatically cause the said third switch to initiate its functioning and selectively hunt and seize the trunk and thereby automatically cause the said second switch to start selectively hunting for and seizing the said second called line to thereby effect a connection from the calling line to the said second called line.

21. In a telephone system, a first switch for connection to a trunk line, said trunk line terminating in a second switch directly controlled in a primary direction movement to select a first group of lines leading to a succeeding switch and in a secondary direction movement to engage a line of the said first group, a second group of lines, the said second switch having an alternative primary movement whereby it will engage a line of the said second group, a third switch terminating a calling line also having access to the said trunk, and means whereby initiating a call on the calling line by a single manual operation will thereby automatically cause the third switch to seize the said trunk and automatically cause the said second switch to initiate the said alternative primary direction movement and seize an idle line of the said second group to thereby effect a connection to an idle line of said second group.

22. In a telephone system, a switch for seizing a called line leading to a springjack thereon, a first relay on the called line which will operate when the called line is seized to cause a first calling lamp to glow, a second relay, means for connecting to the called line through said springjack in responding to the said glowing whereby the second relay will operate and the

said lamp will be extinguished, the said first relay deactuating when the called line is released by the first said switch unseizing, a clearing lamp which will glow from a circuit prepared by the deactuation of the said first relay while the said second relay remains actuated, and means for preventing the said first relay from affecting the said prepared circuit upon its re-actuating resultant to a new call being completed to said called line.

23. In a telephone system, a calling line, a called line, a plurality of tone sources associated with the called line indicative of a plurality of specific conditions of the called line, means whereby the tones from the respective said tone sources are successively operative so that only a single tone will be effective at any time, means for connecting the calling line to the called line, means for applying the respective tones successively audible along the calling line, and means controlled from the called line for disconnecting the tone application to the calling line while a talking connection is maintained between the calling and called line.

24. In a telephone system, a calling line, a called line, a plurality of tone sources associated with the called line indicative of a plurality of specific conditions of the called line, means whereby the tones from the respective said tone sources are successively operative so that only a single tone will be effective at any time, means for connecting the calling line to the called line, and means for automatically applying the respective tones successively audible on the calling line.

25. In a telephone system, a calling line, a called line, a plurality of tone sources associated with the called line indicative of a plurality of specific conditions of the called line, means whereby the tones from the respective said tone sources are successively operative so that only a single tone will be effective at any time, means for connecting the calling line to the called line, means for automatically applying the respective tones successively audible on the calling line, and automatic means for disconnecting the tones from effective connection with the called line.

26. In a telephone system, a calling line, a called line, a plurality of tone sources associated with the called line, but one said tone source effective at a time, means for linking a connection from the calling to the called line, and automatic means for successively applying the respective tones over the talking connection to the calling line.

27. In a telephone system, a calling line, a called line, a plurality of tone sources associated with the called line, but one said tone source effective at a time, means for linking a connection from the calling to the called line, and automatic means for successively applying the respective tones to the calling line.

28. In a telephone system, a calling line, a called line, automatic switches, a plurality of tone sources associated with the called line, but one said tone source effective at a time, means for operating the automatic switches from the calling line to directly link a connection between the said lines, and automatic means responsive to effecting said connection for successively applying the respective tones to the calling line from the called line.

29. In a telephone system, a calling line, a called line, automatic switches, a plurality of tone sources associated with the called line, but one

- 5 said tone source effective at a time, means for operating the automatic switches from the calling line to directively link a connection between the said lines, automatic means for successively applying the respective tones to the calling line, and automatic means for terminating the said applying of the tones.

10 30. In a telephone system, a calling line, a called line, automatic switches, a plurality of tone sources associated with the called line, but one said tone source effective at a time, means for operating the automatic switches from the calling line to directively link a connection between the said lines, automatic means for successively applying the respective tones to the calling line, and automatic means for terminating the said applying of the tones, and automatic means for reapplying the tones.

15 31. In a telephone system, a calling line, a called line, interchangeable tone sources, a plurality of said sources associated with the called line, a specific combination of tones indicative of a specific condition relating to the called line, means for interlinking a connection from the calling to the called line, and means for successively applying the respective associated tone sources over the established connection to the calling line automatically in predetermined order.

20 32. In an automatic telephone system, a calling line, a called line, interchangeable tone sources, a plurality of said sources associated with the called line, a specific combination of tones indicative of a specific condition relating to the called line, means for automatically interlinking a connection from the calling to the called line, and means for successively applying the respective associated tone sources over the established connection automatically in predetermined order.

25 33. In a telephone system, a calling line, a called line, a tone source associated with the called line indicative of a condition of the said called line, means for connecting the calling and called lines, means for automatically applying the tone to the connection, and means controlled over the called line for terminating the tone application and alternatively establishing a talking connection between the said lines.

30 34. In an automatic telephone system, a line, a station, a tone source for connection to the station, means including automatic switches for establishing a connection between the line and the station whereby the tone will be audible at the station to indicate the line connected, and means controlled over the line for disconnecting the tone and for establishing a talking connection between the line and station.

35 35. In a telephone system, a first and a second line, tone sources successively effective, a plurality of said tone sources associated with the first line, means for connecting the said lines, and means effective consequent to the establishment of the connection for causing the said plurality of tone sources to be successively applied automatically, but wherein only a single tone source will be applied at a time to successively indicate corresponding specific conditions relating to the said first line to the said second line.

40 36. In a telephone system, a calling station, a called line, a relay connected to the called line energized responsive to connecting the calling station to the called line, a calling signal device energized by the relay when energized, an answering jack on the called line, an operator's answering plug for cooperating with the jack, means whereby inserting the plug into the jack will de-

45 50 55 60 65 70 75 80 85 90 95 100 105 110 115 120 125 130 135 140 145 150

5 energize the signal device while the relay remains energized, means whereby thereafter disconnecting the calling station will deenergize the relay, and means whereby reconnecting the calling station to the called line to reenergize the relay will reenergize the signal device regardless of the plug being in or out of the jack.

10 37. In a telephone system, calling stations, a called line, a relay connected to the called line energized responsive to connecting a calling station to the called line, a calling signal device energized by the relay when energized, an answering jack on the called line, an operator's answering plug, a supervisory signal device, means whereby inserting the plug into the jack will deenergize the calling signal device, means whereby disconnecting the calling station while the plug is in the jack will deenergize the relay and cause the supervisory signal device to become energized to indicate the condition, and means whereby again connecting a calling station to the called line will reenergize the relay and the calling signal device while not affecting the supervisory signal device, if the plug has been maintained in the jack.

15 38. In a telephone system, calling stations, a called line, a relay connected to the called line energized responsive to connecting a calling station to the called line, a calling signal device energized by the relay when energized, an answering jack on the called line, a second relay cooperative with the first said relay, an operator's answering plug, means whereby inserting the plug into the jack while the signal device is energized will energize the second relay to deenergize the signal device, means whereby thereafter disconnecting the calling station will deenergize the first said relay while the said second relay will be maintained energized, and means whereby again connecting a calling station to the called line to energize the first said relay will reenergize the signal device regardless of the said second relay being maintained energized.

20 39. In a telephone system, a calling station, a called line, a relay connected to the called line energized responsive to connecting the calling station to the called line, a calling signal device energized by the relay when energized, an answering jack on the calling line, a second relay mechanically interlinked with the first said relay, an operator's answering plug, means whereby inserting the plug into the jack while the signal device is energized will energize the second relay to deenergize the signal device, means whereby thereafter disconnecting the calling station will deenergize the first said relay and said second relay will automatically close a path to prepare an alternative circuit path for the signal device, and means whereby again connecting the calling station to the called line to reenergize the first said relay will close the primary or the alternative energizing circuit for the signal device depending upon whether the plug has been withdrawn from the jack or has been maintained in the jack, respectively.

25 40. In a telephone system, a calling station, a called line, a relay connected to the called line energized responsive to connecting the calling station to the called line, a calling signal device energized by the relay when energized, an answering jack on the calling line, a second relay mechanically interlinked with the first said relay, a supervisory signal device energized when the first said relay is normal and the said second relay is energized, an operator's answering plug, means whereby inserting the plug into the jack will de-

30 35 40 45 50 55 60 65 70 75 80 85 90 95 100 105 110 115 120 125 130 135 140 145 150

- will energize the second relay to deenergize the calling signal device, means whereby thereafter disconnecting the calling station will deenergize the first said relay and said second relay will automatically close a path to prepare an alternative circuit path for the calling signal device and close an energizing circuit for the supervisory signal device, means whereby reconnecting the calling station to the called line to reenergize the said first relay will close the primary or the alternative energizing circuit for the calling signal device depending upon whether the plug has been withdrawn from the jack or has been maintained in the jack, respectively, and means whereby if the plug is maintained in the jack after the calling station is disconnected the supervisory signal device will be energized and remain so until withdrawing the plug, regardless of the calling station being or not being again connected to the called line.
41. In a telephone system, a calling station, a called line, a relay connected to the called line energized responsive to connecting the calling station to the called line, a calling signal device energized by the relay when energized, an answering jack on the calling line, a second relay, a supervisory signal device energized when the first said relay is normal and the said second relay is energized, an operator's answering plug, means whereby inserting the plug into the jack will energize the second relay to deenergize the calling signal device, means whereby thereafter disconnecting the calling station will deenergize the first said relay and said second relay will automatically close a path to prepare an alternative circuit path for the calling signal device and close an energizing circuit for the supervisory signal device, means whereby reconnecting the calling station to the called line to reenergize the said first relay will close the primary or the alternative energizing circuit for the calling signal device depending upon whether the plug has been withdrawn from the jack or has been maintained in the jack, respectively, and means whereby if the plug is maintained in the jack after the calling station is disconnected the supervisory signal device will be energized and remain so until withdrawing the plug, regardless of the calling station being or not being again connected to the called line.
42. In a telephone system, a calling station, a called line, a relay connected to the called line energized responsive to connecting the calling station to the called line, a calling signal device energized by the relay when energized, an answering jack on the calling line, a second relay, an operator's answering plug, means whereby inserting the plug into the jack while the signal device is energized will energize the second relay to deenergize the signal device, means whereby thereafter disconnecting the calling station will deenergize the first said relay and said second relay will automatically close a path to prepare an alternative circuit path for the signal device, and means whereby again connecting the calling station to the called line to reenergize the first said relay will close the primary or the alternative energizing circuit for the signal device depending upon whether the plug has been withdrawn from the jack or has been maintained in the jack, respectively.
43. A trunk leading to a first switch which has a directed primary movement and an automatic alternative primary movement, a second and a third switch each having access to the
- trunk, means whereby depending upon which switch seizes the trunk will determine which of said movements the said first switch will be enabled to initially make.
44. A two-conductor trunk leading to, a first switch which has a directed primary movement and an automatic alternative primary movement, a second and a third switch each having access to the trunk, means whereby depending upon which switch seizes the trunk will determine which of said movements the said first switch will be enabled to initially make. 80
45. A trunk leading to a first switch which has a primary movement and an alternative primary movement, a second and a third switch each having access to the trunk, means whereby depending upon which switch seizes the trunk will determine which of said movements the said first switch will be enabled to initially make. 85
46. A two-wire trunk leading to a first switch which has a primary movement and an alternative primary movement, a second and a third switch each having access to the trunk, means whereby depending upon which switch seizes the trunk will determine which of said movements the said first switch will be enabled to initially make. 90
47. A trunk leading to a first switch having a primary movement and an alternative primary movement, the said alternative movement being determined by a specific preliminary control effected over one of the conductors of the trunk, a second and a third switch each having access to the trunk, and means in one of the said switches but not in the other for effecting the said preliminary control consequent to seizing the trunk. 95
48. A two-wire trunk leading to a first switch having a primary movement and an alternative primary movement, the said alternative movement being determined by a specific preliminary control effected over one of the conductors of the trunk, a second and a third switch each having access to the trunk, and means in one of the said switches but not in the other for effecting the said preliminary control consequent to seizing the trunk. 100
49. A two-wire trunk leading to a first switch having a primary movement and an alternative primary movement, the said alternative movement being determined by a specific preliminary transient control automatically effected over one of the conductors of the trunk, a second and a third switch each having access to the trunk, and means in one of said switches but not in the other for effecting the said preliminary control consequent to seizing the trunk. 105
50. A two-wire trunk leading to a first switch having a primary movement and an alternative primary movement, the said alternative movement being determined by a specific preliminary control effected over one of the conductors of the trunk, a second and a third switch each having access to the trunk, and means in one of said switches but not in the other for automatically effecting the said preliminary control consequent to seizing the trunk. 110
51. A two-wire trunk leading to a first switch having a primary movement and an alternative primary movement, the said alternative movement being determined by a control effected over one of the conductors of the trunk, a second and a third switch each having access to the trunk, a slow-releasing line relay in the second switch, a cut-on relay for effecting the seizure of the 115

- 125
- 130
- 135
- 140
- 145
- 150

- second switch and to disconnect the line relay, the line relay deactuating an appreciable time after the actuation of the cut-on relay, a circuit from ground to the said one of the conductors of the 5 trunk and adapted to be closed after the cut-on relay operates and remain closed until the line relay deactuates to transiently ground the trunk to cause the said first switch to automatically effect its said alternative primary movement, 10 there being no grounding of the said one of the conductors consequent to the said third switch seizing the trunk, and means controlled through the seized said third switch for directively operating the said first switch in its primary movement. 15
52. In a telephone system, calling lines in two groups, a single group of trunk lines each trunk line leading to a connecting switch having alternative access to two common groups of called lines, the said switches having directive access to one said group of called lines step controlled and automatic access to the other group of lines by a hunting operation, the said groups of calling lines being specific to a respective said called 20 group, a second and a third group of connecting switches specific to the respective calling line groups, means whereby if a call is initiated on a line of one said calling groups it will thereafter be automatically connected over a trunk of the 25 group of trunks to a line of its specific called group, and means whereby if a call is initiated on a line of the other said calling groups the call can be directly extended over a trunk of the group of trunks to the desired line of its specific 30 called group. 35
53. In a telephone system, calling lines in two groups, a trunk line leading to a connecting switch having access to two alternative groups of called lines, the said switch having directive access to one said group of called lines step controlled and automatic access to the other group of lines by a hunting operation, the said groups of calling lines being specific to a respective called group, connecting switches specific to the respective calling line groups, means whereby if a call is initiated on a line of one of said calling groups the call will thereafter be automatically connected over the trunk line to a line of its specific called group, and means whereby if a call is initiated on a line of the other calling group the call can only be automatically directly extended over the trunk line to the desired line of its specific called group. 40
54. In an automatic telephone system, a branched two-conductor trunk line and terminating switch therefor, a single set of movable connecting terminals of the switch, a plurality of switches specific to each branch of the trunk line for connecting to the trunk line, groups of lines accessible from the first said switch corresponding to said branches, and means responsive to operating one of said switches into connection with the trunk line for thereby barring the first said switch from connecting with the group not corresponding to the branch the first said switch is seized over. 45
55. In an automatic telephone system, a branched two-conductor trunk line and terminating switch therefor, a single set of movable connecting terminals of the switch, a plurality of switches specific to each branch of the trunk line for connecting to the trunk line, groups of lines accessible from the first said switch corresponding to said branches, and means responsive to operating one of said switches into connection with 50
- the trunk line for thereby barring the first said switch from connecting with the group not corresponding to the one of said switches sizing the trunk line. 55
56. In a telephone system, a connecting switch for completing a connection to idle lines of two classes through the same set of switch connecting terminals, two leading-in branches for the switch, and means whereby if one leading-in branch is used for the said connection lines of one said class will be barred against the switch, and if the other leading-in branch is used the converse will hold. 60
57. In a telephone system, a connecting switch for completing a connection to random line of a group of idle lines through the same set of switch connecting terminals, a plurality of leading-in branches for the switch, means for setting the switch into connective relation with the group, and means dependent upon what said leading-in branch is used in the connection which will determine what line of the group the switch will complete the connection to. 65
58. In a telephone system, a connecting switch for completing a connection to the respective sets of terminals of a group of terminal sets, a preliminary test terminal set of said group, two sets of leading-in terminals for the switch, means whereby the switch can be connected with through one of its leading-in terminal sets and thereafter directly operated into testing relation with the said preliminary test terminal set whereupon the switch will automatically selectively test another said terminal set and seize the latter set if idle, and means whereby if the switch is connected with through the other said leading-in terminal set and thereupon directly operated into testing relation with the said preliminary test terminal set the switch will remain as operated. 70
59. In a telephone system, a connecting switch for completing a connection to the respective sets of terminals of a group of terminal sets, a preliminary test terminal set of said group, two sets of leading-in terminals for the switch, means whereby the switch can be connected with through one of its leading-in terminal sets and thereafter directly operated in testing relation with the said preliminary test terminal set whereupon the switch will automatically selectively test another said terminal set and seize the latter set if idle, 75
- means whereby if the switch is connected with through the other said leading-in terminal set and thereupon directly operated into testing relation with the said preliminary test terminal set the switch will remain as operated. 80
60. In a telephone system, a calling line, a connecting switch, a group of lines, means for operating the switch into connection with a line of the group, and means thereafter controlled from the calling line for causing the switch to forthwith selectively test other lines of the group and seize the first idle one tested without first restoring from its operated position. 85
61. In a telephone system, a calling line, a first switch, a connecting switch, a group of lines, means controlled over the calling line for operating the said first switch into connection with the connecting switch and for thereupon operating said connecting switch into connection with a line of the group to effect a connection from the calling line to said line of the group, means thereafter directly controlled from the calling line 90
- 145
- 150

- for causing the connecting switch to automatically selectively test other lines of the group and seize the first idle one tested in a hunting operation without first restoring from its operated position, and means thereafter directly controlled over the calling line for restoring the connecting switch from its operated position without disconnecting the calling line from the connecting switch. 5
62. In a telephone system, a switch, alternative sets of leading-in terminals for the switch, means for connecting with the switch through either set of said leading-in terminals, means directly controlled over the connection with the switch for setting the switch on the set of line terminals of a first one of a group of lines, each line of the group leading from a respective set of line terminals, means whereby if the switch has been controlled over one said set of leading-in terminals the switch may function as an automatic selecting switch to successively test lines of the group in a hunting operation and seize the first idle line tested, and means operative if the switch has been controlled over the other set of leading-in terminals in the said setting of the switch to disable the switch against its said automatic selective function. 10
63. In a telephone system, a switch, alternative sets of leading-in terminals for the switch, means for connecting with the switch through either set of said leading-in terminals, means directly controlled over the connection with the switch for setting the switch on the set of line terminals of the first one of a group of lines, each line of the group leading from a respective set of line terminals, means whereby if the switch has been controlled over one said set of leading-in terminals the switch may function as an automatic selecting switch to successively test lines of the group in a hunting operation and seize the first idle line tested, means operative if the switch has been controlled over the other set of leading-in terminals in the said setting of the switch to disable the switch against its said automatic selective function, and means directly controlled through the said other leading-in terminals after the switch has been set to initiate the said automatic selective functioning of the switch. 15
64. In a telephone system, a switch, alternative sets of leading-in terminals for the switch, means for connecting with the switch through either set of said leading-in terminals, means directly controlled over the connection with the switch for setting the switch on the set of line terminals of the first one of a group of lines, each line of the group leading from a respective set of line terminals, means whereby if the switch has been controlled over one said set of leading-in terminals the switch may function as an automatic selecting switch to successively test lines of the group in a hunting operation and seize the first idle line tested, means operative if the switch has been controlled over the other set of leading-in terminals in the said setting of the switch to disable the switch against the automatic selective function, and means directly controlled through the said other leading-in terminals for restoring the switch from its said set position without disconnecting from the leading-in terminals connected with. 20
65. In a telephone system, a first and a second calling station, each station leading over a line to a switch specific to the use of its said station, a connecting switch common to the use of the stations, first and second classes of called lines in a group, means controlled from the first station over its line to set its said switch into connection with said connecting switch, means for thereupon setting the connecting switch into the position occupied by a line of the first class of called lines and for seizing said line, means thereupon directly controlled from the first station over its line to cause the connecting switch to test lines of the other class of the group hunting an idle line thereof to seize, means controlled from the second station over its line to set its said switch into connection with said connecting switch, means for thereupon setting the connecting switch into the position occupied by the said line of the first class, and means thereupon made operative due to the source of the call to automatically cause the connecting switch to test lines of said other class of the group hunting an idle line thereof to seize. 25
66. In a telephone system, a plurality of successively disposed lines in a group, a switch having access to the group, means for operating the switch into selective relation with a line of the group and to thereupon automatically test following lines of the group hunting an idle line to seize, and means whereby if the switch is operated into selective relation with a different line of the group in lieu of first said line the switch will not automatically selectively test following lines of the group. 30
67. In a telephone system, a plurality of successively disposed lines in a group, a switch having access to the group, means for automatically directly step-by-step operating the switch into selective relation with the first positioned line of the group and to thereupon automatically test following lines of the group hunting an idle line to seize, and means whereby if the switch is operated into selective relation with a different line of the group in lieu of first said line the switch will not automatically selectively test following lines of the group. 35
68. In a telephone system, a plurality of successively disposed lines in a group, a switch having access to the group, automatic control means for operating the switch into selective relation with the first positioned line of the group and to thereupon automatically test following lines of the group hunting an idle line to seize, means whereby if the switch is operated into selective relation with a different line of the group the switch will not automatically selectively test following lines of the group, and automatic control means for thereupon at will directly operating the switch to cause it to hunt for and seize the first following idle line of the group without first restoring the switch from its operated position. 40
69. In an automatic telephone system, a group of lines, a connecting switch for automatically selectively testing over the group of lines hunting for an idle line to seize if the switch is primarily set upon a line of the group and the line is encountered busy, two paths leading-in to the switch, means for seizing the switch over either said path, and means effective dependent upon if a specific one said path is employed in seizing the switch to restrain the switch from advancing from its said set position to hunt for an idle line regardless of the busy or idle state of the line the switch is primarily set upon. 45
70. In an automatic telephone system, a group of lines, a connecting switch for automatically selectively testing over the group of lines hunting for an idle line to seize if the switch is primarily set upon a line of the group and the line is en- 50

- countered busy, two paths leading-in to the switch, means for seizing the switch over either said path, means effective dependent upon if a specific one said path is employed in seizing the 5 switch to restrain the switch from advancing from its said set position to hunt for an idle line regardless of the busy or idle state of the line the switch is primarily set upon, and means thereupon directly controlled at will over the seized 10 path to the switch for causing the switch to automatically selectively test other lines of the group hunting for an idle line to seize.
71. In an automatic telephone system, a group of lines, a connecting switch for automatically 15 selectively testing over the group of lines hunting for an idle line to seize if the switch is primarily set upon a line of the group and the line is encountered busy, second and third switches for alternatively seizing the connecting switch, and 20 means effective depending if a specific one of said second or third switches is in seizure of the connecting switch for causing the connecting switch to be restrained from advancing from its said set position to hunt for an idle line regardless 25 of the busy or idle state of the line of the said set position.
72. In an automatic telephone system, a group of lines, a connecting switch for automatically selectively testing over the group of lines hunting 30 for an idle line to seize if the switch is primarily set upon a line of the group and the line is encountered busy, second and third switches for alternatively seizing the connecting switch, means effective depending if a specific one of said 35 second or third switches is in seizure of the connecting switch for causing the connecting switch to be restrained from advancing from its said set position to hunt for an idle line regardless of the busy or idle state of the line of the said set position, and means thereupon directly controlled 40 at will over the second path to the switch for causing the switch to automatically selectively test other lines of the group hunting for an idle line to seize.
- 45 73. In an automatic telephone system, automatic switches, a connecting switch, a calling station on a calling line leading over a connection of the switches and the said connecting switch, a called line, directive control means for 50 setting the connecting switch upon the called line, means effective to bar the completion of a talking connection from the calling line to the called line if the called line is busy, and means controlled at will over the calling line from the 55 calling station if the set switch is barred for restoring the connecting switch from said set position without destroying the connection between the calling station and the connecting switch.
74. In an automatic telephone system, automatic switches, a connecting switch, a calling station on the calling line leading over a connection of the switches and the said connecting switch, a called line, directive control means for 60 setting the connecting switch upon the called line, means effective to bar the completion of a talking connection from the calling to the called line if the called line is busy, means controlled at will over the calling line from the calling station if the set switch is barred for restoring the connecting switch from said set position without destroying the connection between the calling station and the connecting switch, and means for indicating to the calling station that the restoration has occurred.
75. In an automatic telephone system, a call- 65 ing station, a two-conductor calling line, a connecting switch, a called line, automatic directive control means for setting the switch upon the line to establish a talking connection from the calling station over the calling line to the called line, and means controlled at will from the calling station over the two conductors of the calling line in series for restoring the switch without destroying the connection between the calling station and the switch.
76. In a telephone system, a two-conductor calling line, a called line, a first switch having access to a second switch, the second switch having access to the called line and having a single set of connecting terminals, a directive device on the calling line for operating the switches to complete a connection from the calling line through the switches to the terminals of the called line, and means in the second switch controlled by the directive device over the two conductors of the calling line in series whereby the second switch can be restored at will without destroying the seizure of the second switch by the first switch.
77. In a telephone system, a calling line, a called line, first and second switches, the first switch having access to the second switch, the second switch having access to the called line and having a single set of movable terminals, a directive device on the calling line for operating the switches to complete a connection from the calling line through the switches to the terminals of the called line, and means in the second switch controlled by the directive device whereby the second switch can be restored from the terminals of the called line at will without destroying the seizure of the second switch by the first switch.
78. In a telephone system, a calling line, a called line, first and second switches, the first switch having access to a second switch, the second switch having access to the called line and having a single set of movable terminals, a directive device on the calling line for operating the switches to complete a connection from the calling line through the switches to the terminals of the called line, means in the second switch controlled by the directive device whereby the second switch can be restored from the terminals of the called line at will without destroying the seizure of the second switch by the first switch, and means whereby the directive device can be next operated to again set the second switch as directed.
79. In a telephone system, a trunk, a first switch therefor having a primary movement and an alternative primary movement, the said alternative movement being determined by a specific preliminary control effected over one of the conductors of the trunk, a second and a third switch having common access to the trunk, means only in said second switch for automatically effecting the said preliminary control to cause said alternative primary movement of said first switch responsive to the trunk being connected to by said second switch, and means only directly controlled at will through said third switch when connected to the trunk for effecting said primary movement of said first switch.
80. In a telephone system, a two-conductor trunk, a first switch therefor having a primary movement and an alternative primary movement, the said alternative movement being determined by a specific preliminary control effected over one of the conductors of the trunk, a second and a third switch having common access to the trunk, means only in said second switch for automatically effecting the said preliminary control to cause

said alternative primary movement of said first switch responsive to the trunk being connected to by said second switch, and means only directly controlled at will through said third switch when connected to the trunk for effecting said primary movement of said first switch.

81. In a telephone system, a two-conductor trunk, a first switch therefor having a primary movement and an alternative primary movement, 10 the said alternative movement being determined by a specific transient preliminary control affected over the trunk, a second and a third switch having common access to the trunk, means only in said second switch for automatically effecting 15 the said preliminary control to cause said alternative primary movement of said first switch responsive to the trunk being connected to by said second switch, and means only directly controlled at will through said third switch when 20 connected to the trunk for effecting said primary movement of said first switch.

82. In a telephone system, a two conductor trunk, a first switch therefor having a primary movement and an alternative primary movement, 25 the said alternative movement being determined by a specific transient preliminary control effected over a single said conductor of the trunk, a second and a third switch having common access to the trunk, means only in said second switch for 30 automatically effecting the said preliminary control to cause said alternative primary movement of said first switch responsive to the trunk being connected to by said second switch, and means only directly controlled at will through said 35 third switch when connected to the trunk for effecting said primary movement of said first switch.

83. In an automatic telephone system, a branched two-conductor trunk line and terminating 40 switch therefor, a single set of movable connecting terminals of the switch, a switch specific to each branch of the trunk line for connecting to the trunk line, groups of lines accessible from the first said switch corresponding to said 45 branches, and means responsive to operating one of said switches into connection with the trunk line for thereby barring the first said switch from connecting with the group not corresponding to the branch the first said switch is seized 50 over.

84. In a telephone system, a calling line, a connecting switch, a group of lines, means directly controlled over the calling line for operating the switch into connection with a line of 55 the group, and means thereupon directly controlled over the calling line for causing the switch to automatically selectively test other lines of the group and seize the first idle line tested without first restoring from its operated position.

85. In a telephone system, a plurality of successively disposed lines in a group, a switch having 60 access to the group, means for operating the switch into selective relation with a line of the group when busy and to thereupon automatically test following lines of the group hunting an idle line to seize, and means whereby if the switch is directly operated into selective relation with a different line of the group which is busy in lieu of first said line the switch will be disabled for 65 automatically testing following lines of the group.

86. In a telephone system, a plurality of successively disposed lines in a group, a switch having 70 access to the group, means for operating the switch into selective relation with a line of the group when idle and to thereupon automatically

test following lines of the group hunting an idle line to seize, and means whereby if the switch is directly operated into selective relation with a different line of the group which is busy in lieu of first said line the switch will be disabled for 80 automatically testing following lines of the group.

87. In a telephone system, a plurality of successively disposed lines in a group, a switch having access to the group, means for automatically directly step-by-step operating the switch into selective relation with a line of the group when busy and to thereupon automatically test following lines of the group hunting an idle line to seize, and means whereby if the switch is automatically directly step-by-step operated into selective relation with a different line of the group which is busy in lieu of first said line the switch will be disabled for 85 automatically testing following lines of the group.

88. In a telephone system, a plurality of successively disposed lines in a group, a switch having access to the group, means for automatically directly step-by-step operating the switch into selective relation with a line of the group when 100 idle and to thereupon automatically test following lines of the group hunting an idle line to seize, and means whereby if the switch is automatically directly step-by-step operated into selective relation with a different line of the group which is busy in lieu of first said line the switch will be disabled for 105 automatically testing following lines of the group.

89. In an automatic telephone system, a group of lines, a connecting switch for automatically 110 selectively testing over the group of lines hunting for an idle line to seize if the switch is primarily set upon a line of the group, two path leading-in to the switch, means for seizing the switch over either said path, and means effective 115 dependent upon if a specific one said path is employed in seizing the switch to restrain the switch from advancing from its said set position to hunt for an idle line regardless of the busy or idle state of the line the switch is primarily set upon.

90. In an automatic telephone system, a group of lines, a connecting switch for automatically 120 selectively testing over the group of lines hunting for an idle line to seize if the switch is primarily set upon a line of the group, two paths leading-in to the switch, means for seizing the switch over either said path, means effective dependent upon if a specific one said path is employed in seizing the switch to restrain the switch 125 from advancing from its said set position to hunt for an idle line regardless of the busy or idle state of the line the switch is primarily set upon, and means thereupon directly controlled at 130 will over the seized path to the switch for causing the switch to automatically selectively test other lines of the group hunting for an idle line to seize.

91. In an automatic telephone system, a group of lines, a connecting switch for automatically 140 selectively testing over the group of lines hunting for an idle line to seize if the switch is primarily set upon a line of the group, second and third switches for alternatively seizing the connecting switch, and means effective depending if a specific one of said second or third switches is in seizure of the connecting switch for causing the connecting switch to be restrained from advancing from its said set position to hunt for an 145 150

- idle line regardless of the busy or idle state of the line of the said set position.
92. In an automatic telephone system, a calling station, a two-conductor calling line, a connecting switch, a called line, automatic directive control means for setting the switch upon the called line to establish a talking connection from the calling station over the calling line to the called line, means controlled at will from the calling station over the two conductors of the calling line in series for restoring the switch without destroying the connection between the calling station and the switch, and means for indicating to the calling station that the restoration has occurred. 80
93. In a telephone system, a two-conductor calling line, a called line, a first switch having access to a second switch, the second switch having access to the called line and having a single set of movable connecting terminals, a directive device on the calling line for operating the switches to complete a connection from the calling line through the switches to the terminals of the called line, means in the second switch controlled by the directive device over the two conductors of the calling line in series whereby the second switch can be restored at will without destroying the seizure of the second switch by the first switch, and means for indicating to the calling station that the restoration has occurred. 95
94. In an automatic telephone system, a group of successively disposed lines, a switch having access to said lines, means for automatically directly operating the switch into selective relation with a predetermined line of the group, means whereby if the selected said predetermined line is busy the switch will thereupon hunt from said selected line with automatic selective relation to the remaining lines of the group seeking an idle line of the group, and means whereby if the directly selected line of said group is not said specific line the switch will be disabled for automatic selection with relation to other lines of the group regardless of the idle or busy state of the selected line. 100
95. In an automatic telephone system, a calling line, a plurality of connective switches, a plurality of lines accessible from one of said switches, means directly controlled over the calling line for operating the switches to link a tandem connection from the calling line to a desired random one of said lines, and means including a relay in said one switch controlled over conductors of the calling line in series and used in said operation of said one switch for restoring only said one switch from its connection with said random line, means whereby only the restored switch may thereupon at will be reoperated to effect a connection to a random one of said accessible lines, and means controlled over the calling line for restoring all said switches. 110
96. In an automatic telephone system, a calling line, a group of lines, a connective switch, means for step-by-step operating the switch in a primary movement and thereafter likewise in a secondary movement to select a line of the group controlled over the calling line, and means controlled over the calling line for thereupon at will causing the switch to start a hunting movement from its said selected position in which it will pass over busy lines tested of the group and seize the first idle line tested without restoring said operated movements. 125
97. In an automatic telephone system, a calling line, a plurality of successively positioned lines, a connective switch, means for step-by-step operating the switch in a primary movement and thereafter likewise in a secondary movement to select a line of said plurality controlled over the calling line, and means thereupon at will controlled over the calling line for causing the switch to start a hunting movement from its said selected position in which it will pass over tested busy lines of said plurality and seize the first idle line tested without restoring said operated movements. 135
98. In an automatic telephone system, a calling line, a plurality of normally unguarded lines, a connective switch, means controlled over the calling line for operating the switch in a hunting movement to select an unguarded line of said plurality, and means thereupon at will controlled over the calling line for causing the switch to start a further hunting movement from its said selected position in which it will seize the first unguarded line tested without restoring said operated movements. 140
99. In an automatic telephone system, a calling line, a plurality of lines, a connective switch, means controlled over the calling line for operating the switch in a hunting movement to select a line of said plurality, and means thereupon at will controlled over the calling line for causing the switch to start a further hunting movement from its said selected position in which it will seize a different line of the group without restoring said operated movements. 145
100. In an automatic telephone system, alternative selective switches, a connective switch, a level group of lines belonging to a plurality of classes accessible from the connective switch, a leading-in line for the respective selective switches, means controlled over a random one of said leading-in lines for operating its corresponding selective switch and the connective switch to effect a connection to a line of the group, and means depending upon which selective switch is employed in effecting connection to the connective switch for determining which single one of said classes of lines of the group will contain the line the connection may be completed to by the connective switch. 150
101. In an automatic telephone system, alternative selective switches, a connective switch, a level group of lines belonging to a plurality of classes accessible from the connective switch, a leading-in line for the respective selective switches, means controlled over a random one of said leading-in lines for operating the corresponding selective switch and the connective switch to effect a connection to a line of the group, and means depending upon which selective switch is employed in effecting connection to the connective switch for determining which lines of the group will be thereby barred from connection with by the connective switch. 155
102. In an automatic telephone system, a connective switch, antecedent selective switches to said switch, a leading-in line for the respective selective switches, a level group of lines accessible from the connective switch, a toll line of the group and a local line of the group, automatic means for operating one or the other selective switch and the connective switch over the corresponding said leading-in line to select the group and thereupon connect with a line of the group, and means dependent upon which said selective switch is employed for barring either the toll line or the local line against connection with by the connective switch. 160
103. In an automatic telephone system, a con- 150

nective switch, antecedent selective switches to said switch, a leading-in line for the respective selective switches, a level group of lines accessible from the connective switch, a toll line of the group and a local line of the group, automatic means for operating one or the other selective switch and the connective switch over the corresponding said leading-in line to select the group and thereupon connect with a line of the group, 5 means dependent upon which said selective switch is employed for barring either the toll line or the local line against connection with by the connective switch, and means whereby if the local line is barred it can be unbarred and connected 10 with at will responsive to directive control over said leading-in line employed without again selecting the group.

104. In an automatic telephone system, a connective switch, a two-conductor leading-in line 20 of the connective switch, a plurality of selective switches each having access over said leading-in line to the connective switch, a plurality of levels of lines accessible from the connective switch, directly controlled automatic means for operating a random one of said selective switches and thereupon the connective switch over its leading-in line to select a said level and a line thereof, and means operative dependent 25 upon which said selective switch is employed for barring connection to the line of a specific said level.

105. In an automatic telephone system, a connective switch, a two-conductor leading-in line 30 of the connective switch, a plurality of selective switches each having access over said leading-in line to the connective switch, a plurality of levels of lines accessible from the connective switch, directly controlled automatic means for operating a random one of said selective switches and thereupon the connective switch over its leading-in line to select a said level and a line thereof, and means operative dependent 35 upon which said selective switch is employed for rendering accessible only the lines of a specific said level.

106. In an automatic telephone system, a connecting switch, a two-conductor leading-in line 40 of the connecting switch, a plurality of switches each having access over said leading-in line to the switch, a plurality of levels of lines accessible from the connecting switch, directly controlled automatic means for operating a random one of said switches and thereupon the connecting switch over its leading-in line to select 45 a said level and a line thereof, and specific means in a certain one but not all of the switches cooperative with the connecting switch for barring connection by the connecting switch to the lines of a specific said level only when cooperated with said switch having said specific means.

107. In an automatic telephone system, a connecting switch, a two-conductor leading-in line 50 of the connecting switch, a plurality of switches each having access over said leading-in line to the switch, a plurality of levels of lines accessible from the connecting switch, directly controlled automatic means for operating a random one of said switches and thereupon the connecting switch over its leading-in line to select 55 a said level and line thereof, and specific means in a certain one but not all of the switches cooperative with the connecting switch for rendering the lines of a specific level accessible only when the connecting switch is cooperated with said switch having said specific means.

108. In an automatic telephone system, a two-conductor trunk line, a plurality of kinds of switches accessible to said trunk line, a connecting switch terminating the trunk line, a group of lines accessible from a common set of movable terminals of the connecting switch, and means in the switch seizing the trunk line for determining if the connecting switch will thereupon automatically operate to effect a connection to a line of the group or if the connecting switch will only be thereupon subject to automatic directive control to effect a connection to a line of the group, the determination depending upon the said kind of switch employed. 80

109. In an automatic telephone system, a two-conductor trunk line, a plurality of kinds of switches accessible to said trunk line, a connecting switch terminating the trunk line, groups of lines arranged in specific bank levels accessible from a common set of movable terminals of the connecting switch, the respective said plurality of switches corresponding to specific said levels, and means in the switch seizing the trunk line for determining if the connecting switch will be thereupon automatically operated to effect a connection to a line of one of said groups corresponding to the switch seizing the trunk line. 90

110. In an automatic telephone system, a two-conductor trunk line, a plurality of kinds of switches accessible to said trunk line, a connecting switch terminating the trunk line, groups of lines accessible from a common set of movable terminals of the connecting switch, the respective said plurality of switches corresponding to specific said groups, and means in the switch seizing the trunk line for determining if the connecting switch will be thereupon automatically operated to effect a connection to a line of one of said groups corresponding to the switch seizing the trunk line or if the connecting switch will only be thereafter subject to automatic directive control to effect a connection to a line of one of 105 said groups corresponding to the switch seizing the trunk line. 100

111. In an automatic telephone system, a group 110 of lines, a connecting switch for automatically selectively testing over the group of lines hunting for an idle line to seize if the switch is primarily set upon a line of the group and the line is encountered busy, antecedent switches of two kinds 115 for seizing the connecting switch, and means effective dependent upon which said antecedent switch is employed which will restrain the connecting switch from advancing from its set position to selectively test in hunting for an idle line 120 seizing the trunk line or if the connecting switch will only be thereafter subject to automatic directive control to effect a connection to a line of one of said groups corresponding to the switch seizing the trunk line. 125

112. In an automatic telephone system, calling lines of two classes, a group of successively positioned called lines, a group-selecting connective 130 switch having access to the lines of the group which will automatically test over busy lines encountered, leading-in terminals for the connective switch specific to each class of calling lines, means for extending a connection from a calling 135 line of one or the other class of calling lines to corresponding said leading-in terminals, means controlled over the connection for operating the connective switch to select the first positioned line of the group, and means dependent upon 140 145 150

- which said class the calling line belongs for causing or for disabling the group-selecting function of the connective switch responsive to selecting said first positioned line when busy.
- 5 113. In an automatic telephone system, calling lines of two classes, a group of successively positioned called lines, a group-selecting connective switch having access to the lines of the group which will automatically test over busy lines encountered, leading-in terminals for the connective switch specific to each class of calling lines, means for extending a connection from a calling line to one or the other class of calling lines to corresponding said leading-in terminals, means controlled over the connection for operating the connective switch to select the first positioned line of the group, and means dependent upon which said class the calling line belongs for causing or for disabling the group-selecting function of the connective switch responsive to selecting said first positioned line when idle. 80
114. In an automatic telephone system, calling lines of two classes, a group of successively positioned called lines, a group-selecting connective switch having access to the lines of the group which will automatically test over busy lines encountered, leading-in terminals for the connective switch specific to each class of calling lines, means for extending a connection from the calling line of one or the other class of calling lines to corresponding said leading-in terminals, means controlled over the connection for operating the connective switch to select the first positioned line of the group, means dependent upon which said class the calling line belongs for causing or for disabling the group-selecting function of the connective switch responsive to selecting said first positioned line, and means directly controlled over the calling line for starting the group-selecting function at will when disabled. 100
- 40 115. In an automatic telephone system, a switch terminating a branched trunk having two conductors only, switches for connecting to the trunk over each branch and specific thereto, groups of trunks accessible from the first said switch corresponding to said branches, and means responsive to operating the second said switch into connection with the trunk for thereby barring the switch from connecting with the group not corresponding to the branch the first said switch is seized over. 110
- 55 116. In an automatic telephone system, a switch terminating a branched trunk, switches for connection to the trunk over each branch and specific thereto, two groups of trunks accessible from the first said switch, means in the respective switches for connecting to only one said branch for applying a transient control to the first said switch over the trunk, and means responsive to the transient control for barring the first said switch from thereafter effecting connection in a specific said group. 120
- 60 117. In an automatic telephone system, a switch terminating a branched trunk, switches for connection to the trunk over each branch and specific thereto, two groups of trunks accessible from the first said switch, means in the respective switches for connecting to only one said branch for applying a momentary control to the first said switch over the trunk, and means responsive to the momentary control and effective after the control has ceased for barring the first said switch from thereafter effecting connection in a specific said group. 125
- 75 118. In combination, a telephone line, an automatic switch, means for extending the line to said switch, means for sending a series of impulses to operate said switch to further extend said line, and means in said switch for absorbing the next series of impulses transmitted thereto. 130
119. In combination, a telephone line, an automatic switch, a set of wipers of the switch, terminals of line groups accessible from said wipers, a line relay of the switch, an impulse sender, a circuit including said line relay and sender for directly operating said switch in accordance with a series of impulses to move the wipers to select a desired group of said line terminals, means for maintaining the wipers in the position assumed by said movement although a succeeding impulse is forthwith annexed from the said sender to operate the line relay of said switch, means for causing the wipers of the switch to thereupon advance and connect with one of the lines of said group responsive to said succeeding impulse, last said movement taking place only after the last impulse has terminated, and means for operating said wipers into connection with a line of another of said groups responsive to selecting the desired group and without annexing a succeeding impulse from said sender. 135
120. In combination, a telephone line, an automatic switch, lines terminating therein, an impulse sender, a circuit including said switch and sender for directly operating said switch in accordance with a series of impulses, means in said switch for rendering ineffective the next set of impulses while maintaining said switch in its set position, and means thereupon automatically operated for causing said switch to select an idle line. 140
121. In a telephone system, a line, an answering terminal for said line at its far end, a call signal permanently companion to said terminal, means operated over the line from along its near end for causing the call signal to indicate a call, means for causing the call signal to maintain said call indication, a common manual connective terminal for cooperation with said answering terminal to effect connection from said manual terminal to the line, means automatically responsive to the act of cooperating said manual terminal with said answering terminal for effacing said call indication and for also preparing a new circuit path for said call signal for thereby enabling said call signal for being thereupon subject to operation again from along the near end of the line to indicate a new call, and means for causing said call signal to be again operated involving said new circuit path to indicate a new call responsive to control over the line from along the near end thereof while maintaining the manual connective terminal in its said cooperated condition. 145
122. In a telephone system, a line, an answering terminal for said line at its far end, a call signal permanently companion to said terminal, means operated over the line from along its near end for causing the call signal to indicate a call responsive to connecting along the near end of the line in extending a call connection to said line, means for causing the call signal to maintain said call indication, a common manual connective terminal for cooperation with said answering terminal to effect connection from said manual terminal to the line, means automatically responsive to the act of cooperating said manual terminal with said answering terminal for effacing said call indication and for also preparing a new circuit path for said call signal for thereby 150

- enabling said call signal for being thereupon subject to operation from along the near end of the line to indicate a new call, and means for causing said call signal to be again operated involving said new circuit path to indicate a new call responsive to destroying said connection to the line and thereafter again effecting a connection to the line while maintaining the manual connective terminal in its said cooperated condition.
123. In a telephone system, a line, an answering terminal for said line at its far end, a call signal permanently companion to said terminal, means operated responsive to closing a circuit path including a conductor of the line for causing the call signal to indicate a call, means for causing the call signal to maintain said call indication, a common manual connective terminal for cooperation with said answering terminal to effect connection from said manual terminal to the line, means automatically responsive to the act of cooperating said manual terminal with said answering terminal for effacing said call indication and for also preparing a new circuit path for said call signal for thereby enabling said call signal for being thereupon subject to operation again to indicate a new call, and means operated responsive to thereupon opening and thereafter again closing said path including a conductor of the line for causing the call signal to again operate to indicate a new call regardless of the fact said manual terminal has been maintained cooperated with said answering terminal following its initial cooperation.
124. In a telephone system, a line, an answering terminal for said line at its far end, a call signal permanently companion to said terminal, means operated responsive to closing a circuit path including a conductor of the line for causing the call signal to indicate a call, means for causing the call signal to maintain said call indication, a common manual connective terminal for cooperation with said answering terminal to effect connection from said manual terminal to the line, means automatically responsive to the act of cooperating said manual terminal with said answering terminal for effacing said call indication and for also preparing a new circuit path for said call signal for thereby enabling said call signal for being thereupon subject to operation again to indicate a new call, and means operated responsive to thereupon opening first said circuit path for further preparing a new circuit path for said call signal, and means responsive to thereupon closing said opened path for causing the call signal to again operate by

control over said new circuit paths to indicate a new call regardless of the fact said manual terminal has been maintained cooperated with said answering terminal following its initial cooperation.

80

125. In a telephone system, a line, an answering terminal for said line at its far end, a call signal permanently companion to said terminal, a pair of relays, means controlled over the line for operating one of said relays for in turn operating said signal to indicate a call, a common manual connective terminal for cooperation with said answering terminal to effect a connection from said manual terminal to the line, means automatically responsive to the act of cooperating said manual terminal with said answering terminal for energizing and thereby operating the other of said relays for effacing said call indication, means thereupon prepared by said act whereby responsive to the restoration and re-operation of first said relay for again operating said call signal to indicate a new call while maintaining said other relay energized.

85

90

95

126. In a telephone system, a line, an answering terminal for said line at its far end, a call signal permanently companion to said terminal, a pair of relays, means controlled over the line for operating one of said relays for in turn operating said signal to indicate a call, a common manual connective terminal for cooperation with said answering terminal to effect a connection from said manual terminal to the line, means automatically responsive to the act of cooperating said manual terminal with said answering terminal for energizing and thereby operating the other of said relays for effacing said call indication, means thereupon prepared by said act whereby responsive to the restoration and re-operation of first said relay for again operating said call signal to indicate a new call while maintaining said other relay energized.

100

105

110

115

120

125

127. In a telephone system, only two relays, a local circuit path, means for energizing one of said relays for in turn energizing said circuit path, means for thereafter energizing the other of said relays for in turn deenergizing said circuit path, and means whereby deenergizing and thereafter energizing said one relay will re-energize said circuit path.
